SHEET FEEDING DEVICES

Derk J. Oldenboom, Endicott, N. Y., assignor to International Business Machines Corporation, New York, N. Y., a corporation of New York

Application July 22, 1953, Serial No. 369,700

16 Claims. (Cl. 271—3)

This invention relates generally to record feeding devices and more particularly to sheet and envelope feed devices for taking such sheets singly out of a magazine and bring them to printing positions and away therefrom at high speed.

One of the main objects of the invention is to provide means for feeding and positioning various sizes and thicknesses of sheets, documents and envelopes by common means. The devices include adjustable magazine and stacker structures as well as adjustable gripping chain advancing devices for grasping sheets of varying widths and lengths. The variations in size of documents such as envelopes may be spread over quite a range of differences wherein the widths may vary from 5" to 12" and the depth or lengths of the forms may vary from 3" to 12". Then there is also the question of thickness, which may be varied from a thin sheet of only about .004 of an inch in thickness up to a heavy card or envelope with two or more layers having the combined thickness of about .050 of an inch.

Another object of the invention is the provision of means for selecting the headspacing position of the first line of print on each document. Such a setting is coordinated with the particular length of sheet handled at the time, and for that reason the adjustable headspacing controls are coordinated with the sheet length setting controls so that the devices are prearranged to bring a certain size sheet to any desired first line position for the initiation of printing thereon. In most instances the object is to print names and addresses on envelopes, but of course the machine is adapted for many other kinds of recording work because of the flexibility in handling documents of different size and efficacy to position such documents wherever desired with respect to the printing line so that one or more lines of alphabetic, numerical or chronological data may be recorded thereon as desired.

Part of the flexibility noted hereinbefore with respect to positioning the sheets as desired to receive printing at various places is imparted by the coordination with tape controlled platen advancing means. For any particular run of printing, a special prepunch feed control tape is made to determine the stopping positions of the sheet feeding devices so that the arrangement of print thereon is made invariable in many respects and automatic without need of attention on the part of the operator. The feed control tape not only determines the positioning of recording, but it also determines the timing of the harmonic motion of the feeding devices so that the sheets are picked up gradually and moved with high speed and stopped with a gradual decelerating motion. The feed control tape has sets of advanced predicting control perforations for controlling a two speed clutch between the driving means and feed chains, whereby between starting and stopping positions, there is always an interval of slow speed control before and after high speed operation through friction clutches between the driver and the driven parts of the sheet feed.

- An object of the invention is to provide auxiliary sheet feeding devices suited for cooperation with any electrically controlled high speed printer. The loose document carriage of this invention is a self-controlled but auxiliary feed device. It is self-controlled in the sense of containing a separate drive motor, two speed clutch, a platen and feed control tape therefor, clutches, cam contacts and control magnets and relays, but it is dependent for reception of printing by connections to and cooperation with an electrically controlled printer such as that exemplified by the machine disclosed in the copending patent application of A. B. Crowell, Serial No. 227,671, filed on May 22, 1951, now Patent No. 2,687,087. The present carriage is suited for coordination with printing devices such as those of a record controlled tabulator by electrical controls for coordination with the record feeding, group control and printing cycles of the tabulator so that the printing and feeding operations fall in the proper sequence.
- Another object of the invention is the provision of sheet feeding means designed to operate at such high speeds and with such coordination that an exceptional number of recording operations may be made without having the record feeding devices call for a delay in the operation of the tabulator. The purpose of the design is to permit the tabulator to record as many as 400 lines a minute and at times permit the movement or ejection of a sheet as much as 4" without calling for hesitation or delay on the part of the tabulator. It is evident from these figures that the addressing of ordinary size envelopes may be carried on without loss of cycle time on the part of the recorder.
- Another object of the invention is to provide simple magazine slanting devices to provide for feeding varying thicknesses and lengths of documents. It is found that by changing the angle of presentation of the leading edge of a document coming out of the magazine it is possible to feed more advantageously rather heavy material by simple picking and feed roller devices.
- Another object of the invention is the provision of means for varying the line spacing distances from 6 to 8 lines per inch as selected by manipulative devices without calling for a replacement of the common feed control tape.
- Another object of the invention is the provision of common adjusting means for varying the tension of the feeding chains and also adjusting for variable sheet thicknesses by shifting the platen with respect to the type. These adjustment means are so arranged that the chain tension may be varied or made settable in conjunction with taking care of differences in sheet thickness.
- Another object of the invention is the provision of an automatically effective deflector or shutter for guiding the leading edge of each document as it is brought into position around the front face of the platen and directly opposite the inking ribbon. The shutter is mechanically operated and timed to coincide with the advance of the leading edge of each incoming document.
- Another object of the invention is the provision of a vacuum arm picking mechanism cooperating with the magazine for successive feeding of sheets one by one into sets of feeding rollers positioned to act as intermediaries between the vacuum lifter and pairs of clips on the feeding chains. A guide venting control is provided to afford rapid release of a picked sheet. If the vacuum arm fails to pick up a sheet the machine is stopped. The clutches for the vacuum feed arm and oscillator are electronically controlled and a variable commutator pulse delay is provided to control the starting time of the vacuum feed to put the sheet in the grippers at print time when the feed chains are stationary. Other relay controlled delay devices for the vacuum feed clutch is provided for

use in key controlled run in cycles to prevent too rapid entry of sheets before the grippers are ready for them.

Another object of the invention is the provision of sheet alignment controls to insure that the incoming sheets are properly presented. The two endless chains have grippers to engage both sides of leading edges of sheets. At both sides are sheet sensing levers and relays controlled thereby with contacts in series with a printer running circuit. As long as both sheet sides are squarely presented the printer continues in operation through jointly operated contacts.

Another object is to provide a compact two speed clutch mechanism with clutch operation of uniform torque independent of clutch plate spacing and thickness. There is also the feature of separate adjustment for each of the low and high speed control mechanisms of the clutch.

An object of the invention is to improve the stacker by providing an automatically positioned pressure plate for backing upstacked documents. The plate is mechanically shifted as controlled by a clutch with a magnet operated by contacts closed as the space is closed in the stacker reception area.

A feature of the hopper or magazine construction is the hinging of it on adjustable pivots to be raised and lowered and swung to the best angle of presentation for the documents to be picked off one by one.

Another object of the invention is the provision of means for making accessible the area between the vacuum picking arms and the chain clips for the removal of jammed documents between the feed rolls on occasions of improper feeding.

The invention is illustrated as an improvement over tape controlled feeding device of the kind shown in the A. W. Mills et al. Patent No. 2,531,885, filed on August 9, 1945, and issued on November 28, 1950, and copending application of J. H. Bakelaar et al., Serial No. 230,206, filed on June 6, 1951, now Patent No. 2,684,746.

Other objects of the invention will be pointed out in the following description and claims and illustrated in the accompanying drawings, which disclose, by way of examples, the principle of the invention and the best mode, which has been contemplated, of applying that principle.

In the drawings:

Fig. 1 is a side elevation view of the entire document handling carriage.

Figs. 2 and 2a when taken together show a sectional elevation view of the magazine, the feed chains and the receiving stacker.

Fig. 2b is a plan view showing the two scales for controlling the adjustment of the feed devices according to sheet length and head spacing requirements.

Figs. 3 and 3a when taken together show a front elevation view of the two speed clutch at the right and the pair of feed chains and the control connections thereto,

Fig. 4 is a side elevation view partly in section showing the stacker controls,

Fig. 5 is a sectional view taken along line 5—5 in Fig. 4 showing the manipulative portion of the adjustable setting means for the stacker,

Figs. 6 and 6a when taken together show a plan view illustrating the means for mounting and adjusting the feeding chains at the points where the clips on the chains grasp the sheets. A pair of magnets SSM is for operating sheet stops and another pair HSM is for operating the chain clips to grasp the leading edge of the halted sheet,

Fig. 7 is a side elevation view of the headspacing control mechanism which is shiftable with magnets HSM to grasp the sheet at a selected place in its path and at a desired position relative to the printing line which it later reaches at the platen.

Fig. 8 is an end view partly in section taken along

line 8—8 in Fig. 7 and showing the clip operating portion of the headspacing controls,

Fig. 9 is a sectional elevation view taken along the line 9—9 in Fig. 6 and showing the chain clips and sheet lever contacts in the interior of the headspacing mechanism,

Fig. 10 is a detail view partly in section taken along the line 10—10 in Fig. 6 and showing one of a pair of sheet stopping controls for determining the initial position of an incoming sheet before it is grasped by the clips on the feed chains,

Fig. 11 is a sectional detail view showing one of the clips on the feed chain and how it is cammed to a dotted idle position and later effective for grasping a sheet and pinching it between one of the clip arms and an extending portion of the feed chain,

Fig. 12 is a sectional elevation view taken along line 12—12 in Fig. 3 and showing the upper portion of the path of the chains as they are elevated to carry the sheets into the stacker,

Fig. 13 is a detail sectional view taken along line 13—13 in Fig. 12 and showing the means for confining the feed chain and opening a clip or gripper thereon as it passes the position wherein the sheet is released from the chain and deposited in the stacker,

Fig. 14 is a detail sectional view taken along the line 14—14 in Fig. 13 and showing an operating roller and its effect upon the chain clip for releasing a sheet at the stacker,

Fig. 15 is a sectional elevation view taken along the line 15—15 in Fig. 1 and showing the various frames and the means for adjusting the inner chain supporting frames to adjust them according to sheet length and headspacing control,

Fig. 16 is a detail view taken along line 16—16 in Fig. 15 and showing the worm and worm wheel gear connections for adjusting the sheet carrying frames,

Figs. 17 and 17a when taken together show the sheet picker portion of the feed devices including the vacuum feed arms for picking the sheets successively out of the magazine, and the view is taken along the line 17—17 as shown in Fig. 2a,

Fig. 18 is a sectional elevation view of the driving mechanism for operating the vacuum feed arms and is taken along the line 18—18 in Fig. 17,

Fig. 19 is also a sectional elevation illustration of the driving means for the vacuum feed devices and associated sheet picking mechanism and is taken along the line 19—19 directly alongside the previously mentioned section line in Fig. 17,

Fig. 20 is a central sectional elevation view of the interior of the sheet feed at the magazine and picking station and is taken along the line 20—20 in Fig. 17,

Fig. 21 is a sectional elevation view showing the two clutch controls for the vacuum feed oscillating arms and the feed roller drive controlled, respectively, by magnets VCM and SF, and it is taken along the line 21—21 of Fig. 17,

Fig. 22 is a partial elevation view showing the hopper adjusting scale and pointer,

Fig. 23 is a sectional elevation view taken along the line 23—23 in Fig. 17a and alongside the other section 22—22 and showing the gearing connections for adjusting and operating the magazine feed,

Fig. 24 is an enlarged detail view showing one of the vacuum feed arms,

Fig. 25 is a section taken along the line 25—25 in Fig. 24 and showing the valve opening arrangements inside the head of a vacuum feed arm,

Fig. 26 is an end view taken along the line 26—26 in Fig. 2a and showing the frame of the magazine and the adjusting means cooperating therewith,

Fig. 27 is an elevation view of the gearing on the outside of the two speed clutch for driving the sheet feeding devices,

Fig. 28 is a side elevation view partly in section showing the gearing and controls cooperating with the two speed clutch.

Fig. 29 is a sectional elevation view taken along the line 29—29 in Fig. 28 and showing some of the gearing in the two speed clutch.

Fig. 30 is a sectional plan view taken along the line 30—30 in Fig. 29 and showing the interior construction and driving connections for the two speed clutch.

Fig. 31 is an outer elevation view taken along the line 31—31 in Fig. 28 and showing the electrical controls for the two speed clutch.

Fig. 32 is a sectional elevation view of the record-card feeding portion of a tabulator,

Fig. 33 is a cam contact chart showing the timing of the electrical controls,

Figs. 34a—34e when taken together form a wiring diagram of the electrical controls of the feed devices.

A short preliminary explanation may be given to tell of all the main parts of the sheet feeding device by reference to Figs. 2 and 2a wherein it is noted that the drive motor M has belt feed connections to many portions.

The sheets, envelopes or documents are put in hopper or magazine H from which they are picked out one at a time by the vacuum arms V which swing the leading sheet edge into feed rollers and into guide strips G which lead it toward the feed chains C of the device.

At pulley 10 the drive is communicated to the constantly operating shaft of the two speed clutch 2SC, Fig. 3a, which is effective to impart graduated low and high speed movement to the square shaft S which carries the drive sprockets 11 for the two feed chains C. The endless chains, Fig. 2, travel over a pistol shaped path wherein at E a pair of the regularly spaced clips CS thereon grasp the leading edge of an incoming sheet and carry it to the right and under shaft S and then up to print receiving position at platen P. The clips CS are spaced regularly at 4" intervals along the chains. Revolving in synchronism with movement of the sheet past platen P is the periphery of a tape feed drum 231, Fig. 3a, on shaft S to carry a feed control tape TP, Fig. 1, with spaced feed control indicia for determining the positioning of print on the sheet. After printing is completed the sheet is carried upward on the chains C, Fig. 2, and away from the platen P, over the top sprocket 13 and down into the stacker ST.

It is noted that at the lower left part of the path of the chains C there is a double reversal of direction around the sprockets 14 and 15. This is arranged so that an adjustable head space frame carrying such sprockets may be shifted along the chain to actuate the clips thereon at different positions and yet maintain the chain taut in all sprocket positions. A drive belt 16 is guided with a similar double reversal of path so that the hopper frame carrying an actuated pulley 36 may be shifted towards the motor M according to various sheet lengths without changing the belt.

The machine is supported on a portable base 20 (Fig. 1) on which is a pair of braced angle iron frames 19 across the front of which is secured a casting 21 that carries the drive motor M and the vacuum pump VP. When the sheet feeding machine is to be assembled with the printing transcriber it is wheeled along the floor and brought against the printer with the platen P facing the typebars T. A shaft 8 in casting 21 is engaged by lifting hooks or latch clamps 12 pivoted in the transcriber frame 9. Another shaft 17 is in frame 21 and it is engaged by a notched formation 18 of frame 9. When levers are applied to the notched clamps 12 and swung clockwise to lift pins 8, and a tie rod is inserted through the lugs of castings 9 and 21, the entire sheet feed machine is lifted, clamped and locked into position against the printer.

Five pairs of side frames (Figs. 1, 6, 15 and 17) comprise the holders for most of the sheet handling or carriage

mechanisms. The front and rear main frames 22 and 23 (Fig. 1) are fastened to the front casting 21. Rear frame 23 is the taller of the two and carries on the inside of the top area most of the stacker mechanism. Fastened to the insides of the main frames 22, 23 are slanted tracks 24 which provide guides and supporting means for the part of the device including the sheet magazine and the single sheet vacuum arm feed parts.

Extending across the area between the upper parts of the two main frames 22, 23, Fig. 2, are three triangularly arranged tubes 68, 69 and 70 which act as slide supports for the frames 76 and 77, Figs. 3 and 3a, for carrying the chains C. Another tube 7, Fig. 2, is a spacer near the bottom of the two main frames.

Extending outside the front main frame 22, Figs. 1 and 15, is a bracket 71 carrying the head spacing scale HSS, Fig. 2b. Also on the outside of frame 22 is an adjustably secured arm 72, Fig. 1, carrying the tensioning feed roller 6 for the feed control tape TP. Fastened to the outside of the rear frame 23, Fig. 3a, is the two speed clutch mechanism 2SC which acts as an intermediary between the motor drive and the square shaft S. Also on frame 23 is the belt driven stacker mechanism ST Fig. 3.

Journalled in both main frames, Fig. 3a, is a threaded shaft 73 with a hand wheel for controlling the spacing of the chain carrying frames 76 and 77 by shifting the frame 76 laterally.

Extending to the left of the main frames, Fig. 1, and 30 slidably supported thereon is a pair of feed unit frames 25 and 26 carrying the hopper H. In Figs. 1, 17 and 17a it is seen that the feed frames 25 and 26 have fastened to their outer faces a pair of slanted slides 27 each of which is fitted inside the pairs of tracks 24 which are affixed inside the main frames 22 and 23. Within the feed frames 25, 26 is the single sheet picker in the form of vacuum suction arms V (Fig. 2a) and a feed mechanism to carry a picked sheet to the chains, said mechanism being spaced between the frames and partly supported by spacing plates 31 and 32. Fastened on the outside of frame 25, Fig. 1, is a bracket 74 carrying the sheet length scale SL, Figs. 2b and 15, for gauging the proper position of the feed frame along the tracks 24 to correspond with the length of the sheet or envelope it is desired to feed. In Figs. 2, 6 and 15 it is seen that racks 41 and 42 are fastened to the inner faces of feed frames 25 and 26 and are used to move the feed unit gradually to adjust for sheet length. A shaft 44, Fig. 15, extends across the entire machine and is supported in bearings in the main frames and carries two pinions 43 meshing with teeth on the undersides of the racks 41 and 42. An extending manipulative rod 34 operates helical gears 35 and 36 (Fig. 16) to drive worm 37 and rotate worm wheel 38 and its connected shaft 44. By so turning shaft 44 it is possible to shift the entire feed unit frame 25, 26 and racks 41, 42 with respect to the fixed frames and shaft 44. A somewhat similar shaft 46 (Fig. 15) is pivoted in bracket blocks 33, Fig. 6, extending from the sides of the inner head space frames and has pinions 45 meshing with the upper teeth of the racks 41, 42 for adjusting the head spacing frames. Side frames 25 and 26 are slotted around the shafts 44, 46 to permit free feed unit adjustment past the extending shafts.

The head space carriage comprises front and rear frames 39 and 40, Figs. 6 and 6a, spaced by rods 75 and 65. A stiffener 78 is fastened between the rods. Journalled in brackets 33 fastened to the outer faces of the head space frames 39 and 40 is the adjusting shaft 46 which has the pinions 45 meshing with racks 41, 42. When shaft 46 is rotated with a hand wheel, the head spacing frames and mechanism therein is shifted with respect to both the main frames 22 and 23 and the feed unit frames 25 and 26, and therefore spaced differentially 70 to stop and engage the leading edge of the incoming sheet

or envelope on the chains in a desired position with respect to a point on the chain path which is known to correspond to the print receiving line at the platen.

With reference to Fig. 2 it may be pointed out again that both chain frames such as frame 77 are slidable along tubes 68, 69 and 70 according to a desired sheet width. Now it is also noted that the head spacing devices are required to carry the sprockets 14 and 15 to the left or right to take along therewith the head spacing selection controls. Since head space frames 39, 40, Figs. 6, 6a, do not move laterally along with the chain adjustment, there must be provided intermediate frames 79 and 80 slidably mounted on rods 65, 75 and carrying bearings for chain sprockets 14 and 15. Enlarged washers 81 (Fig. 7) fastened to the side of frames 79 and 80 extend upward to embrace the lower edges of chain frames 76 and 77 and follow along therewith when adjustments are made for sheet width. In other words, intermediate frames 79, 80 are keyed to both sets of chain and head space frames to partake of both adjustments and thereby shift the pairs of intermediate sprockets 14 and 15 axially and longitudinally in accordance with both adjustments for sheet width and head spacing.

The drive connections from the motor M, Fig. 1, are communicated to various parts of the machine by means of drive belts. Motor M, Fig. 2, is fastened to the inside wall of the front frame 21. Around one motor pulley is the belt 1 for driving the pulley 10 on the main shaft of the two speed clutch to be considered in detail herein-after. On the same axis is a pulley 48 with a vertically strung belt 3 which at its top end is diverted by idlers and passed around a slanted stacker drive pulley 49. Referring again to Fig. 1 it is noted that below motor M is a vacuum pump VP which is driven by a belt 2 between them. Extending to the left of motor M is a belt 16 which is caught around the feed unit drive pulley 51. Belt 16 is then drawn down and back in a double reverse direction around an idler pulley 47 movable with pulley 36 and a fixed pulley 5 on an adjustable extension 28 of the main frame 23.

When feed frames 25, 26 are adjusted inwardly for short sheet lengths, the pulley 51 and idler 47 are moved therewith as noted in phantom on Fig. 2, but the overall length of belt 16 remains constant as extended by the fixed pulley 5.

Also on the feed frames 25, 26 is another drive connection including a belt 4 which is drawn around pulley 51 and used to drive pulley 52 and shaft 54 which is the driver for the vacuum pickup feed arms and feed rollers.

Before going into detail regarding the various feed units, a general outline may be given of the sheet or envelope transport from the hopper H (Fig. 2a) to the stacker ST. The sheet is picked up by a vacuum arm V which turns back the upper edge of the leading sheet in the hopper H and oscillation thereof shifts the leading edge around to be grasped between feed rollers 56, 57 and 58 which are geared together. The feed rollers then transport the sheet through parallel sets of flat flexible spring steel guides G forming a channel through which the transported sheet is guided a variable distance between the hopper and the point of grasping by clips CS on the parallel endless chains C. The upper spring steel guides G are coiled and spring wound in containers 60 adjacent the upper feed rollers and are secured to a bar 55 fastened to a cross plate 61 on an angular bracket 66 fixed to the head space unit. The lower spring steel guides G are fastened on arms 64 near the feed rollers and at the right they are weighted after passing through guides fastened to plates 62 and 63 of the head space unit. The purpose of this type of guide fastening is to provide flexibility to permit positioning of both the hopper and the head space unit because of the necessity for handling sheets of various lengths and also providing for different spacing of the initial printing line so that various

head spaces may be provided according to the nature of the document handled.

On the head space unit frame are sheet stop control magnets SSM (Figs. 6 and 10) each with an armature 82 formed with an abutment normally resting on fixed block 83 for stopping the leading edge of an inserted sheet in order to align it prior to the time that it is gripped by the clips CS on the feed chains C. The pair of endless feed chains C, Fig. 2, are carried by sprockets 11, 85, 13, 10 18, 87, 14 and 15 which are so located that the sheet is carried from the throat 55 past the platen P and up to the stacker ST where fixed rollers 67 (Fig. 2) open the pair of operative clips CS allowing the sheet to drop into the stacker. All of the chain guiding sprockets except the sprockets 11 are free running and they are the exception because they are operated by the two speed clutch to form the driving means for the chains.

A pair of sheet sensing levers 88, Figs. 8 and 9, have been provided to sense the sides of the leading edge of the incoming sheet and exercise electrical controls to stop the feeding devices if a sheet fails to be properly grasped and advanced. A pair of support plates 89 are fastened to the head space side frames 79 and 80. These support plates 89 provide a pivotal mounting 90 for the guide levers 88. 20 Mounting blocks 91 of magnets SSM have a milled slot S which permits the spring urged sheet levers to enter the slot 872. A micro switch CL1 is operated by the extended portion on the lever 88. Each time a sheet is advanced to the platen, the sheet levers 88 and cooperating switches 25 CL1 and CL2 are operated together to indicate that the sheet is being advanced correctly.

As mentioned earlier there are flexible spring steel guides G, Figs. 2 and 2a, which guide the document from the feed rolls to the throat. Lower tape G is fastened to block 64 fastened to shaft 93. Shaft 93 is fastened in front and rear feed frames 25 and 26. On the other end of bottom tape G is weight W which is raised and lowered by the movement of the feed frames. A curved guide 60 62 fastened to the head space carriage provides a smooth track for tape G. Each top guide tape G is fastened to bar 55, fastened to the head space carriage, and is coiled in a container 60 fastened to a bar 98. Bar 98 (see also Fig. 20) is fastened to brackets 99 pivoted on shaft 93 and biased in a counterclockwise direction by spring 100, 40 Fig. 18. Means for raising bar 98 is provided by a handle 101 fastened to shaft 102 journaled in rear feed frame 26 and rear vacuum feed frame 30. Fastened to shaft 102 is lever 103 on which link 104 is pivotally mounted. Link 104 connects lever 103 to a camplate 105 pinned to shaft 50 106. Camplate 105 contacts an extending stud 107, Fig. 23, on bracket 99. A similar camplate 105 is pinned to shaft 106 at the other end. Manipulation of lever 101 and the consequent counterclockwise rotation of camplates 105 causes brackets 99 to raise the bar 98. Pressure feed 55 roll 57 is journaled in brackets 99 and is opened whenever brackets 99 are rotated. Bar 98 and pressure roll 57 are thus raised to permit removal of document jams.

It is noted hereinbefore that the feed devices are designed to handle sheets or envelopes of various sizes. In 60 Figs. 19, 20, 23 and 26 there are shown the means for adjusting the hopper or magazine H for the maximum and minimum lengths of sheets. The entire hopper H is pivoted at 109, Fig. 20, on its back plate 110 which is shiftable upward and angularly inward toward the vacuum feed arms V. By means of a series of gears 111, 112 and 113, Fig. 23, a shaft 114 is caused to rotate when a hand wheel 115, Fig. 1, is operated. A bevel gear 116, Fig. 23, fastened to shaft 114 meshes with another bevel gear 117 fastened to a shaft 118. Shaft 118 is journaled angularly 65 in brackets 119 and 120 fastened to the side of the hopper frame member 29. Another bevel gear 122 fastened to shaft 118 meshes with a bevel gear 124 fastened to threaded shaft 125 which is journaled in vertically arranged brackets 120 and 129. A slide 130 carrying hopper pivot stud 109 has an extended threaded portion which 70 75

engages threaded shaft 465. Slide 130 moves in tracks 142 and a slot in the outer frame 29 so that when hand wheel 115 is rotated, slide 467 is moved. A similar mechanism is employed in connection with the other frame 30, said mechanism also being gear connected to the shaft 114 that is journaled in brackets 119 fastened to both the front and rear sub frames 29 and 30. The back plate 110, Fig. 20, of the feed hopper H is pivotally mounted on stud 109 in slide 130 on the rear sub frame 30 and is further supported by a threaded pivot 109 on a similar slide in the front sub frame. Adjustment of pivots 109 in such a manner determines the portion and angle of the leading document edge to be bent forward by the vacuum arms V.

The hopper tilt mechanism comprises a lever 143, Fig. 2a, containing a series of saw tooth notches 144 and is pivotally mounted on a bracket 145, Fig. 26, attached to the hopper back plate 110. A plate 146 containing a stud 147 is attached to the main side frame 30. The angle of adjustment of hopper is varied by depressing lever 143 and shifting the hopper back plate 110 to the desired position. In order to facilitate selection of correct positioning for the different size sheets a scale pointer 148, Fig. 22, is pivotally mounted alongside a scale plate 149 attached to the slide 130. The pointer is biased counterclockwise by a spring 186 and an operating pin 187 in block 188 on the back plate 110 operates the scale pointer.

In order to lift the lower boxlike hopper support to accommodate the various sized documents, the following is provided. Referring to Figs. 2a, 20 and 26, there it is shown that the hopper wall 110 is provided with stiffening bars 190. The wall is also provided with ears for receiving the pivot pins 109 of the adjustable carriers 130 shown in Fig. 2a. The lower hopper support unit is a box formed with side plates 191 and 192 bent as channels around wall 110 and bars 190 and is slidably disposed for cooperation with the wall along the lower portion thereof. The means for positioning the hopper support unit upward with respect to the wall 110 (Fig. 26) comprises a long screw 193 journaled for rotation in bearing brackets 194 and 195 both of which are secured to the wall 110. Rotation of said screw is effected by means of a hand crank 196. This screw is threaded inside a long nut bracket 197 attached to a double flared plate 198 secured to the side plates 191 and 192. The rotation of the screw accordingly moves the plate 198 and connected hopper sheet support box 191 upward and downward with respect to the wall 110.

Since it is now noted how the hopper H is adjustably connected to the feed unit, at this point it is well to consider the means for holding the sheets in the hopper and the devices for pressing them forward against the hopper back plate 110. The sheets are placed on the top plate 199 of the box 191, Figs. 2a, 20 and 26. Attached to the top of the lower hopper support box is a pair of brackets 200 and 201 between which is strung a rod 203.

Slidably mounted on rod 203 is a lower pressure bar assembly 204. The upper and lower pressure bar assemblies are similar in design but the mounting of the upper pressure bar is different and is described hereinafter.

The lower pressure bar assembly 204 comprises an L-shaped casting 205, Fig. 26 into which is fastened a rod 206 extending to the left. Rotatably mounted on rod 206 and spring urged in a clockwise direction is a pressure plate 207 fastened to arms 208 which have bearings on rod 206 and carry between them a handle bar 209. The means of retracting the pressure bar assembly for loading is provided by the handle bar 209 also fastened to arms 208.

A bar 211 fastened to box 199 provides a track for a roller 212 rotatably mounted on L-shaped casting 205. A latch 213, of a common type, is rotatably mounted on the side of casting 205. Latch 213 engages track 211 in the position shown. A pin 214 fastened in bracket 200,

rotates the latch 213, releasing the latch when the pressure bar assembly is retracted to an extreme position.

The means for urging the pressure bar assembly 204 against the documents is provided by a spring urged lever 216. Lever 216 is formed with an articulating slot 218 and is pivoted at 217 on a shaft extending through side plate 191. A shouldered screw 219 passes through slot 218 and is fixed in casting 205 to provide a sliding connection whereby lever 216 may push the entire lower pressure unit 204 to the right, Fig. 2a. Lever 216 is also attached to a knob 220 through an intermediary ratchet and pawl (not shown) so that shaft 217, Fig. 26, and a connected torsion spring 221 may be adjustably set to bias lever 216 variably in a clockwise direction. Means of dampening the spring action is provided by a dash pot 223 which is pivotally mounted on the inside 191 of the hopper box. A rod 224 is pivotally mounted on lever 216 connecting it to dash pot 223.

An upper pressure bar assembly 225 is similar in construction to the lower pressure bar assembly and is provided for use only with long documents when the lower hopper box is in the lower positions. A guide assembly 226 is pivotally fastened at 227 to the rear sub frame 30. A latch mechanism provides a total radial adjustment of 20° in three increments. A latch 228 slidably mounted in the guide assembly 226 is formed with a stepped slot 229 and spring urged against a stud 230 fastened in rear sub frame 30 to provide a lock for the radial adjustment. The upper pressure bar assembly 225 is adapted to be rotated 180° in a counterclockwise direction about rod 203', Fig. 26, to remove the upper pressure bar 207' from the path of short documents when the lower hopper box is in the raised position.

Document side guides are provided to adjust for various widths of documents. A fixed guide 233 is fastened to the right hand side of the hopper box top 199. A rod 234 is fastened in brackets 200 and 235 fastened to the hopper box. An L-shaped bracket 236 is slidably mounted on rod 234. A thumb screw 237 is used to clamp the bracket 236 to rod 234. A guide bar 238 shaped like 233 is fastened on bracket 236 and extends forwardly to form the left side of the paper guide.

At this point it will be well to consider how the sheets are taken out of the hopper one by one. A series of 45 vacuum cup arms V act as a picker mechanism to swing out the leading edge of the foremost sheet and put it between feed rollers which then forward it to the chains C by means of the guides G. Most of this vacuum feed mechanism is in the upper left corner of the space between feed unit plates 25 and 26, Fig. 2a. The mechanism is shown in greater detail in the views Figs. 17-21, inclusive.

In Figs. 17, 17a it is seen that between the feed unit frames 25 and 26 there are other side frames 29 and 30 on which some of the vacuum picker controls are hung. Extending between frames 29 and 30 are the plates 31 and 32 fastened thereto and also carrying feed unit parts. It will be recalled that the drive into the vacuum feed was by means of a belt 4, Fig. 2a, for turning pulley 52. The shaft 54 on which pulley 52 is fastened, Fig. 17, is 55 journaled in frames 240 and 241 fastened to plates 31 and 32. A gear 242, fastened to an extended portion of pulley 52, meshes with a gear 243 fastened to a shaft 244, Fig. 20. Shaft 244 is journaled in frames 26 and 239. A gear 246 fastened to shaft 244, Fig. 18, meshes with a 60 large gear 247 fastened to feed roll shaft 248. Gear 247 meshes with an idler gear 249 pivotally mounted on a screw 250 fastened in bracket 251. Gear 249 meshes with another idler gear 252 rotatably mounted on a stud 253 fastened in bracket 251. Gear 252 meshes with gear 65 254 on feed roll shaft 56. Idler gears 249 and 252 are required because feed roll 56 separates from feed roll 58 during feeding of relatively thick documents which would otherwise cause partial gear demeshing with its attendant wear.

The gears have been calculated to provide a single

plane of meshing without interference between the larger gear 247 on feed roll 58 and the small gear 254 on feed roll 56 but still provide the correct surface speed. This precludes the necessity for a two plane gear train used on other forms of feeding machines.

Feed roll 57, Fig. 20, is driven by a gear 247', Fig. 17a, on the front end of feed roll shaft 248, Fig. 20, which meshes with an idler gear rotatably mounted on shaft 93. Another idler gear (also not shown) is rotatably mounted on a stud fastened in a bracket such as bracket 99 but on the other side. The gear train produces a drive to a gear fastened to feed roll 57. It is therefore apparent that whenever power is applied to the motor M of the loose document carriage the feed rollers 56, 57 and 58 will be in continuous motion.

Referring again to Fig. 17 a spring clutch 256 of well known design under control of armature 257 controlled by a vacuum feed clutch coil VCM governs the operation of gear 258 pinned to the driven part of the clutch.

The clutch is of the type where inner adjacent driving and driven rings are surrounded by a coil spring normally loose but when released by the armature, coils around and grasps both rings for a driving connection. Gear 258, Fig. 19, meshes with a gear 260 fastened to shaft 261. Shaft 261 is journalled in frames 241 and 26 and has fastened to it a gear 262 and cam 263, Fig. 18. Gear 262 meshes with the gear 131 fastened to shaft 132, journalled in frames 29 and 30. Shaft 132 has fastened to it cams 264, 265, 266 and the VF contact cams 133, Fig. 17a. Shafts 261 and 132 and the cams and gears thereon are all under control of spring clutch 256 and are caused to rotate only when clutch magnet VCM is energized. Gear 260 also drives another large gear 259 which is on a shaft 255 that is part of an oscillation selection clutch shown in Fig. 21 and noted hereinafter.

As noted hereinbefore, means are provided for separating the feed rolls and guide tapes. In conjunction with this mechanism there is provided a means for separating the feed roll 56 from feed roll 58 to facilitate feeding various thicknesses of documents. A dial 268, Fig. 23, is numerically graduated and is fastened to a shaft 269 journalled in frames 26 and 30. A lock lever 270 normally biased in a clockwise direction by a spring contacts the serrated surface of dial 268 holding the dial in a selected position. An eccentric surface 271 on shaft 269 coacts with a lever 272 pivotally mounted on a stud 273. Lever 272 is normally biased in a clockwise direction by a spring 274. Plate 251 on which a roller 277 is mounted is biased in a counterclockwise direction around pivot point 275, Fig. 23, by spring 276 so that roller 277 and lever 272 are held in constant contact. It is therefore apparent that counterclockwise rotation of lever 272 due to the rotation of the eccentric surface 271 of shaft 269 coacting with lever 272 will cause lever 272 to rotate counterclockwise on stud 273 effecting clockwise rotation of plate 251. Clockwise rotation of plate 251 will cause feed roll 56 rotatably mounted thereon to be moved away from feed roll 58. A similar mechanism is provided at the other end of feed roll 56.

As mentioned earlier, flat curved spring steel guides G and feed roll 57 are raised by lever 105, Fig. 18, for removal of document jams. Means are also provided for simultaneously raising feed roll 56. Lever 279 rotatably mounted on shaft 102, is biased counterclockwise by spring 280 so that lever 279 contacts a roller 281 mounted on plate 105. When plate 105 is rotated counterclockwise by handle 101 and linkages 103 and 104, lever 279 is rotated clockwise. Clockwise rotation of lever 279 causes it to coact with a roller 282 mounted on lever 272 causing lever 272 to rotate counterclockwise. Counterclockwise rotation of lever 272 in contact with roller 277 mounted on plate 251 causes plate 251 and feed roll 56 mounted thereon to rotate clockwise away from central feed roll 58. Each end of feed roll 56 is raised by a similar mechanism. A micro switch 283 fastened to the rear

feed frame provides a safety interlock to prevent machine operation when feed rolls 56 and 57 are opened. Lever 103 contacting the plunger in micro switch 283 keeps the machine circuit closed.

5 For the purpose of engaging inserted sheets, Fig. 20, feed roll 56 is caused to oscillate about 28° around feed roll 58 to a position for pinching the leading edge of a sheet bent back by arms V. Rollers 56 are interspersed between arms V for clearance. It is noted hereinbefore, 10 Fig. 19, that a shaft 255 is driven by the sheet feed gearing. Turning now to Fig. 21 it is seen that shaft 255 extends partway into a well known form of spring clutch 285 controlled by sheet feed magnet SF. In Figs. 17 and 18 it is seen that the driven end of the clutch 255' 15 carries an eccentric 286. Onto eccentric 286 is adjustably clamped an operating arm 287 which is articulated with a lever 288 pivoted at 289. A link 290 connects lever 288 to the bail 291 pivoted about the feed roll shaft 248. Plate 251 pivotally mounted on bail 291 is thus caused to oscillate each time the bail is operated. Feed roll 56 pivotally mounted on plate 251 is thereby caused to oscillate through the 28° arc mentioned above by rotation of clutched eccentric 286. The armature 292, Fig. 21, under control of coil SF interposes the clutch drive 20 to provide selective oscillations of feed roll 56.

The leading document D is carried by the vacuum feed arms V, Fig. 20, from the hopper to the feed roll 56. A vacuum arm frame 294, Figs. 17 and 18, is journalled between front and rear feed frames 25 and 26. The series 30 of vacuum arms V with cups 296 are mounted on the vacuum frame 294 which is normally latched in a retracted position. Vacuum frame 294 is pivotally mounted at one end on an adjustable stud 295, Fig. 17a, fastened in the front feed frame 25.

35 At the other end a slotted bushing 297, Fig. 17 pressed into vacuum frame 294 pivotally mounts the frame in flanged sleeve 298 which in turn is pressed into junction box 299 fastened to rear feed frame 26. A gasket inserted between the vacuum frame 294 and flanged sleeve 298 40 provides a vacuum seal at the pivot point. An inner capped slotted sleeve 300 is journalled in sleeve 297. A box shaped duct 301 fastened to rear feed frame 26 connects the junction box 299 to the vacuum hose 302.

45 Referring now to Fig. 18 vacuum frame 294 is moved to the position for swinging out the next document by the following mechanism. A slotted cam follower link 303 slidably mounted on shaft 261 has a roller 304 rotatably mounted thereon. Slotted cam follower link 303 is pivotally mounted at 305 on an extended portion of vacuum frame 294. Cam 263 cooperates with roller 304 to produce reciprocating motion of link 303 which imparts oscillatory motion to vacuum frame 294. A cam controlled latch lever 306 normally biased in a clockwise direction around stud 307 by spring 308 has mounted thereon a roller 309. A cam 264 contacts roller 309 each cycle, 50 rotating latch 306 counterclockwise and releasing vacuum frame 294. Vacuum frame 294 thus released is urged in a counterclockwise direction by spring 311 under control of the cam 263 to pick off the next document.

55 60 The previously mentioned slotted sleeve 300, Fig. 17, oscillates within slotted sleeve 297. The valve action thus produced controls the vacuum to the orifice in cups 296. As vacuum frame 294 is rotated counterclockwise to pick up the next document, sleeve 300 is rotated relatively clockwise by its extended portion 313 striking block 314 fastened to sub frame 30, opening the valve. After vacuum arm frame 294 has gripped the document, cam 263 returns it to the position of Fig. 20. Stud 321 fastened in a cam follower arm 319 strikes extended portion 320 on slotted sleeve 300 rotating it counterclockwise thus closing the valve. At this same time a second stud 322 on cam follower arm 319 strikes the arm of a crank shaped venting device 323 pivotally mounted on vacuum frame 294 for venting the vacuum opening therein. Venting device 323 is normally biased in a clockwise direction 65 70 75

by a torsion spring (not shown) so that rubber cap on the horizontal arm is held against a venting port in the vacuum frame. This venting system provides rapid relaxation of the document permitting greater feeding speeds. Cam follower arm 319 is normally biased in a counterclockwise direction around pivot stud 324 and held against a stop stud by spring 325.

Cam 265 fastened to shaft 132 intermittently contacts a roller 326 on the lower end of arm 319. Rotation of cam 265 thereby controls the vacuum cut off and venting of all the vacuum pick up arms V.

A means of retracting the remaining documents in the hopper pack after one document has been removed by the vacuum arms V is provided by a tined bail 328 (Fig. 20). A cam follower arm 329 (Fig. 19) pivotally mounted on a stud 330 is connected to a link 331. A spring 332 attached to link 331 biases cam follower 329 counterclockwise so that a roller 333, rotatably mounted on follower 329, is held in constant contact with the cam 266 mounted on shaft 132. Pivotally mounted on link 331 is an arm 334 to which is fastened a trunnion 337 passing through frame 30 and secured to the bar 335 which is the bail frame for the tines 328, Fig. 17. The other end of tined bar 335 is journaled on a stud 336 in sub frame 29. As cam 226 rotates, Fig. 19, the linkage described above causes tined bail 335 to oscillate, alternately releasing a document and retracting the pack.

In Fig. 1 is shown the hose 302 which connects the vacuum frame 294 to the valve associated with the vacuum pump VP. A by-pass valve 344 in the vacuum line provides means for adjusting the vacuum from a maximum to a minimum to suit the particular weight and thickness of sheet or envelope being fed. A combined lever and indicator 345 attached to the by-pass valve 344 permits an adjustment of the valve in accordance with a calibrated scale.

Figs. 24 and 25 show that the vacuum cups 296 have adjustable size suction openings which vary according to the rotation of the outer disk or ring 341 which has holes to be notched with the holes drilled in the arm V. A pair of flexible rings 340 seated in counterbored holes in the arm casing provide seals for closing the ports 342 when the disk 341 is rotated.

Provisions are made for adjusting the feed frames 25 and 26 according to predetermined sheet length and the head space carriage 39-40 according to the desired blank space at the top of each sheet. The shaft 44, Fig. 15, is journaled in the main frame 23 and further supported in the frame 347 of a speed reduction unit fastened to the other main frame 22. Secured to shaft 44 is a pair of gears 43 which mesh with racks 41 and 42, Figs. 6 and 6a, fastened to the feed frames 25 and 26. Shaft 44, Fig. 15, is connected to the shaft 34 by gearing within the speed reduction unit as already noted. A clamp lock 348 operated by a lever is provided to hold shaft 34 in the selected position thereby preventing movement of the feed frame after it is set in position and during the time that the head space carriage is being adjusted and also during ordinary machine operation.

A head space carriage mechanism held within frames 39 and 40, Figs. 6 and 6a, is also arranged to be adjusted. The shaft 46 is journaled in brackets 33 fastened to the front and rear head space frames 39 and 40 and has secured thereon gears 45 which mesh with the racks 41 and 42 fastened to the side frames 25 and 26 of the feed frame. Shaft 46 is also provided with a clamp block lever 349 which operates to clamp shaft 46 in the desired adjusted position.

A translucent sheet length and head space indicator 350, Figs. 2b and 15, is fastened to a bracket 351 which is fastened to the head space frame 39 and projects through slots in both of the other frames 22 and 25. A scale HSS with markings representing inches and fractions of inches is used to indicate the setting of the head space and is fastened to a bracket 71 that is secured to the outside of

the main frame 22. Another similar scale SL is provided to indicate settings of sheet length and is fastened to a bracket 74 on the feed frame 25 and arranged in slanted alignment with the other scale HSS and adjacent thereto so that both scales appear on opposite sides of the indicator 350.

It is noted hereinbefore that the head space carriage and the intermediate frames adjacent thereto are moved in conjunction with each other for head spacing adjustment and that movement of the intermediate frames is carried on independently along with the adjustment of the chain frames according to sheet widths; in other words, the intermediate frames receive two kinds of adjustment, longitudinally for head spacing and laterally for sheet width spacing.

Considering first the arrangement of the head space frames 39 and 40, Fig. 6, it is seen that they are properly spaced by rods 65 and 75 and have mounted thereon brackets 353, Figs. 7 and 15. Secured to the brackets but insulated therefrom are a series of contact bars 354. A series of contact fingers 355, Fig. 7, are fastened to but insulated from the intermediate frames 79 and 80 and are situated so as to cooperate with the contact bars 354. The center contact bar 354 is the common electrical supply while the upper contact bar supplies one side of an electrical circuit for operating the clip closing coil HSM and the lower bar 354 supplies another circuit for the operation of the magnet SSM controlling the aligning stops in the head space carriage. At this point it may be noted that the function of the head space carriage and the electrical controls therein is to arrange to stop the leading edge of an incoming sheet at a differential position with respect to the continuously moving chains and when in such a selected head space position to arrange to have the clips on the chains opened and closed in such a position as to grasp the leading edge of the sheet relative to the position of the platen so that when the sheet arrives at the platen it will be spaced the desired number of inches and fractions of inches from the first printing line to the top of the sheet.

There are two aligning stop mechanisms in the head space carriage. They are fastened inside of each intermediate frame 79 and 80, Figs. 6 and 6a. A rod 357 is fastened in the mounting plate 89, Fig. 7, which is fastened to intermediate frame 79. A clamp screw 358, Fig. 8, secures the mounting block 91 to rod 357. Magnet SSM, Fig. 10, is mounted in a yoke 359 which is fastened to mounting block 91. Projecting from the mounting block 91, Fig. 8, is a post 360 on which a paper stop 82 is pivotally mounted. Mounting block 91 is clamped to rod 357 to permit adjustment of the armature paper stop 82 with relation to the lower paper guide 361. This guide 361 (Fig. 9) is fastened to the bracket 83 on the intermediate frame and is of sufficient width to cooperate with the paper stops 82 in all positions.

As the chains C are driven through the head spacing carriage the clips CS thereon are opened at selected positions and then permitted to close again after the leading edge of the sheet is projected between the jaws of the open clip and an extending portion 362 on the chain. The open and closed positions of the clips CS are shown in Figs. 9 and 11 where an enlarged showing reveals the manner in which the clips are mounted with internally coiled springs 363 normally functioning to hold the clips shut.

A clip opening device, Figs. 7, 8 and 9, is fastened to the outside of each of the intermediate frames 79 and 80. A roller 364 is rotatably mounted on an arm 365 fastened to hub 366, Fig. 6. The hub is pivotally mounted on rod 357 and has secured thereto a lever 367. A magnet HSM is provided to control the operation of the clip opening device. The armature 368, Fig. 7, of coil HSM extends through a slot 369, Fig. 8, in lever 367. Formed in armature 368 is a notch 370, Fig. 7, against which lever 75 367 is normally biased in a counterclockwise direction by

a light spring 371, the upper edges of the slot 369 cooperate with the side walls of the notch 370. A support for coil HSM is provided in the form of a yoke 372 fastened to intermediate frame 79. When the coil HSM is energized, the armature 368 is rocked in a clockwise direction to release the lever 367 which then rocks counterclockwise to put the roller 364 in the path of the upwardly extending arm of clip CS. However, then the roller 364 is not latched down and it merely rises and falls idly over the upper arms of the passing closed clips CS. It is only when the magnet HSM is deenergized that the armature 368 is in a latching position to catch the lever when it rocks down to the left and hold the roller 364 down positively.

A yoke 374, Fig. 8, is fastened to each of the intermediate frames 79 and 80 so that the center line of the yoke and the center line of roller 364 are arranged as shown in Fig. 9. Yoke 374, Fig. 8, is so proportioned that pins 375 in the chain C are guided within the jaw-like lower projections of the yoke 374. As the chain C, Fig. 9, is driven around sprockets 14 and 15, clip CS is biased in a clockwise direction by the inner coil spring 363, Fig. 11. The depressed arm of clip CS approaching the top of sprocket 15 contacts the top of roller 364, Fig. 9, rotating the roller carrier arm 365 counterclockwise. Such rotation of arm 365 causes lever 367 to relatch on armature 368 should coil HSM be deenergized at that time. With lever 367 latched, clip CS is opened as it reaches the bottom point just beyond the lower right of the center line of roller 364. If at this time, armatures 368 are operated by energization of magnets HSM then clips CS will be spring closed to grip the leading edge of the sheet and carry it along on the chains through the printing positions at the platen and up into the stacker. Since the clips CS are spaced 4" apart, armatures 368 are held energized for sheets or envelopes over 4" in length so that clips CS are not opened until the tail end of the sheet is beyond the grasping line and free of the clips. For documents of a length less than 4" magnets HSM are not held energized and therefore lever 367 may be latched counterclockwise and each pair of clips CS are opened and closed each time they encounter roller 364.

At this point consideration may be given to the means for supporting and adjusting the chains C by shifting laterally the frames 76 and 77 which carry the sprockets on which they are mounted. It was noted with reference to Fig. 2 that the three tubes 68, 69 and 70 are triangularly arranged supports which are fastened on main frames 22 and 23 to hold the chain assemblies between them. On frames 76 and 77 are bushings 378, 379 and 380 slidably mounted on the three tubes. Running through the center of the unit is a threaded shaft 73 with a nut-like bushing 84 keyed to frame 77. On shaft 73, Fig. 3a, is an adjusting crank 377 for turning the shaft to shift frame 77 laterally for positioning to carry a desired width of sheet.

Rotation of the adjusting crank 377 causes the chain frame 77 to move laterally to the right or left. A stop limits the movement of the right hand frame 77 toward the right. Provisions are made for moving both of the chain frames concurrently by means of a threaded hollow shaft 78 on the threaded shaft 73, the former being manipulated by means of a hand wheel 381 attached thereto. The chain frame 76 at the left is provided with a nut portion 382 to engage the threaded area on the hollow shaft 78 so that rotation of hand wheel 381 causes the left chain frame 76 to move to any desired position. With the crank 377 locked to the hand wheel 381, rotation of hand wheel 381 causes both front and rear chain frames 76 and 77 to be shifted concurrently. In order to lock the crank 377 to hand wheel 381 there is provided a pin attached to the crank control knob which enters one of four holes in the hand wheel 381 so that both shaft 73 and 78 rotate in unison.

A brake is provided in the form of plastic blocks 383

pivoted against the main frame 22 and drawn together so as to grip the tube 78. The frictional resistance thus provided normally prevents the tube 78 from rotating when the inner shaft 73 is rotated for adjustment of the single chain frame 77.

A square shaft S has fastened to it a bearing collar 384 and a gearing hub 385. Slidably mounted on shaft S and journaled in the front of main frames 22 and 23 are the chain sprockets 11. Bars 386 fastened to the chain frames 76 and 77 enter grooves in the sprockets 11 so that the sprockets follow the movement of the chain frames. Rotatably mounted within the square shaft S is a shaft 387 to which the control tape contact roller 231 is fastened. A gear 388 fastened to shaft 387 drives the feed control tape contact roll 231 in equal increments regardless of the setting of the line space mechanism for either 6 or 8 lines to the inch. The square shaft S is under control of the two speed clutch 2SC which drives the gear 389 fastened to shaft S. A brush block 128, Fig. 1, is pivotally mounted at 127 on frame 22 and biased in such a manner that the brushes thereon are held in contact with the feed control tape TP and adapted to scan the perforations appearing therein and fall into contact with roll 231 whenever perforations appear under the brush tips. The feed tape is held taut by the adjustable arm 72 and roller 6 previously mentioned and the tape is held centralized by pin feed devices on the main feed roll 231 so that control by the tape is exercised in the same manner as set forth in patents previously identified.

30 A paper guide plate 390, Fig. 2, is fastened to the front end of the main frames 22 and 23. Above plate 390 is a shutter 391, Fig. 3, fastened to side arms 392 pivoted at 393 and controlled mechanically. Belt 3 which is continuously driven by the pulley 48, Fig. 2, on the motor drive shaft is lengthened to operate the shutter in addition to its other function for controlling the stacker mechanism. The belt 3, Fig. 3, is guided by pulleys 394 and 395 and drives the other pulley 396 which is fastened to a part of an interior shaft. Pulleys 394 and 395 are rotatably mounted on a stud 398 which also serves as a support for the plate 399. A shaft 400 is journaled in bearings in the two main frames 22 and 23 and is enclosed by the chain frame tube 69. A cam 401 is fastened to shaft 400 for the purpose of operating under control of 45 the drive. A cam follower arm 402 is biased counterclockwise, Fig. 2, by a spring and is pivotally mounted on stud 393. A stud in the cam follower arm 402 engages a slot in the shutter side arm 392 to connect the two for operation.

50 When the shaft 400 is operated cams 401 attached thereto are revolved causing the shutter 391 to be opened at printing time and closed when a sheet or envelope is being advanced into the printing position. By so operating the shutter the leading edge of the inserted document is 55 prevented from being caught against the ribbon or the adjacent ribbon holding or print supporting elements. The shutter holding arms and operating cams are duplicated at the other side of the machine.

Platen P, Fig. 3a, is rotatably mounted on the shaft 114 60 journaled in sprocket carriers 85 fastened in chain frames 76 and 77. Sprocket carrier 85 is threaded so that a clamp 404 can be attached thereto. A wire ring on shaft 114 is forced into a bevel in sprocket carrier 85 by clamping nut 404 to secure shaft 114 on which platen P is mounted 65 in the desired print receiving position.

A scale 405, Fig. 3, fastened to chain frame 76 is slidably mounted in a slot in chain frame 77. A hairline indicator 406 fastened to rear chain frame 77 provides indication of sheet width.

70 A second translucent scale 407 attached to the front chain frame 76 is marked with a dual scale divided into increments of sixths and eighths of inches. Clip CS fastened to chain C passes under the scale to give visual indication of the corresponding position of the trailing edge of the other initial grasping of clip CS which is hidden

in the head space carriage where the document is gripped by clips on entering. When a new head space is selected for a document, the space mechanism is energized until the trailing edge of clip CS corresponds with the desired point on the engraved scale. The control tape TP is then placed on the machine and the proper head spacing will be obtained on all succeeding documents of this group.

Means is provided for adjusting platen P to compensate for various thicknesses of documents. An adjusting knob 410, Fig. 3, is fastened to a threaded shaft 411. The threaded portion of shaft 411 engages a threaded stud 412 fastened in a block 413 which supports sprocket 13. Block 413 is slidably mounted in slot 414, Fig. 12, in chain frame 77. Shaft 411 is guided by a bracket 415 which is adjacent to another bracket 416 for carrying a threaded shaft 417. Bracket 416 is fastened to chain frame 77. Also fastened to threaded shaft 411 is a gear 418. Gear 418 meshes with gear 419 fastened to the threaded shaft 417 journalled in bracket 416 fastened to chain frame 77. The threaded portion of shaft 417 engages a threaded block 420 which supports sprocket 85. Threaded block 420 is slidably mounted in a slot 421 in chain frame 77. Rotation of knob 410 will cause block 420 to move the platen P toward the type and will move block 413 downward maintaining the same chain tension. If bracket clamp 415 is released from shaft 411, and clamp 416 is held with its shaft in position, rotation of knob 410 will cause block 413 to move. Movement of block 413 increases or decreases the chain tension depending upon the direction block 413 is moved.

A pointer (not shown) is biased around a pivot point by a spring so that an operating point contacts the adjusted threaded block 420. The pointer thus indicates the selected document thickness on a scale fastened to the chain frame 77. Since there are two chain frames, there are two indicators and two adjusting knobs 410 and mechanisms for moving the platen.

Because of the need for high speed movement of the chain feed it is desirable to graduate the speed of initial and final movement of the chains. Therefore, the drive to the square shaft S for sprockets 11 is not direct but instead works through high and low speed friction clutches as selected automatically by electrical controls governed by predetermined spacings of feed control holes in the tape TP.

The drive clutch is of the two-speed frictional variety and is always started with the slow speed disks engaged and for short movements of one or a few line spaces the slow speed portion of the clutch is the only portion used. In instances of sheet advances of over seven line spaces the clutch drive is automatically shifted to the high speed side of the clutch so that for advances of one or more inches the movement of the sheet is made quite rapid to keep pace with the printing cycles of the high speed printer. Because of a slight amount of slippage in the friction drive the change of feeding from rest to slow speed and then to high speed is levelled off to an amount of graduation into almost harmonic or sign wave change of rate of high speed. The same gradual change from rest to high speed is reversed in the case of stoppage and this is brought about automatically by control through sensing devices cooperating with the feed control tape TP. Since abrupt stopping at high speed is not advisable the tape is designed to give both early and final indications of desired stopping positions. An early feed indicia indication is sensed shortly before the stopping position is reached and this controls the clutch to shift from high speed down to slow speed operation. This is followed by sensing the final feed control indicium on the tape and complete stoppage of the tape and sheet terminating the low speed drive. The control tape is provided with a pair of feed control perforations for each stopping control position to predetermine the print receiving positions of the sheet or envelope synchronized therewith. In cooperation with the indicia of the feed control tape are sensing means includ-

ing a series of thyratron tubes for rapidly calling into action clutch shifting and sheet stopping relay controls. Related pairs of speed change and stop control tape brushes are connected to pairs of thyratrons with capacitive coupling to cause rapid circuit changes and corresponding rapid speed changes and stops.

In addition to the frictional speed control clutches of the drive there is also interposed a clutch of the positive tooth type for precise line spacing and long feed movements. By a joint operation of the frictional and ratchet type clutches it is possible to get precise short and long space movements. There is further provision for shifting the interposing gearing between the clutches and the sprocket drive shaft so that the gear ratio is selectively proportioned for either 6 or 8 lines to the inch according to the manipulations of the operator.

Referring to Figs. 2 and 28 it is noted that the drive from the motor M is communicated to the pulley 10 by means of belt 1. Fixed to the same shaft with the pulley 10 is a pinion 424 which is on shaft 422 journalled in the side frames 23 and 423. From pinion 424 there is a train of gearing including gears 425 and 426, Fig. 29, for driving the fast speed clutch and gears 427 and 428 for driving the slow speed clutch. After the drive passes through either clutch it is communicated to the common operator, pinion 430, in mesh with both driven gears 431 and 432 on the driven side of both friction clutches.

Before going into detail regarding the clutch mechanism it may be pointed out that the resultant drive from the friction and ratchet clutches is always communicated to gears 434 and 435 fastened together on shaft 436 shown in Fig. 29. Gear 435 operates through the two gears 437 and 438 on a plate 439 fastened to the clutch frame 440. It provides a constant uniform spacing movement to the gear 388, shaft 387 and the tape TP regardless of the choice of 6 or 8 line spacing. The other gear 434, however, is the driver for the chains and it works through meshing with a wide gear 441, Fig. 3a, which is connected to a smaller gear 442, and both are slidably mounted on a shaft 443. As shown with an adjustment lever 446 tipped to the left the wide gear 441 is in mesh with both the driving gear 434 and a driven gear 444 (see also Fig. 27) which is rotatably mounted on shaft 436 but secured to a larger gear 445 in mesh with the chain drive gear 389. Thus, for six lines to the inch the drive is rather direct through wide gear 441. However, when a link 447, Fig. 3a, is pulled to the left, the lever 446 is rocked clockwise on its pivot on bracket 448, the gears 441, 442 are then shifted so that gear 441 is taken out of mesh from gear 444 and smaller gear 442 is meshed with larger gear 445. There results a change in ratio of drive movement to space with eight lines to the inch rather than six.

Returning again to consideration of the two speed clutch arrangement, it will be noted that the frictional clutch plates are arranged in two arrangements 450 and 451, Figs. 29 and 30.

The present high speed document forms carriage employs the two separate friction clutches; the low speed clutch 450, Fig. 30, which is used for line spacing operations and the high speed clutch 451 which is used for ejecting operations. The motive power needed to drive the related clutch discs 452 and 453 is supplied by the drive shaft 422, Fig. 29, to which gear 424 is fixed, and intermediate gears 425 and 427. As shown in Figs. 23 and 30, clutch discs 452 and 453 are driven by gears 428 and 426, respectively, which in turn are driven by gears 427 and 425. Thus, the clutch discs 452 and 453 rotate as long as the carriage drive motor operates. Inner comparison clutch discs 454 and 455, Fig. 30, are keyed to gears 432 and 431 freely mounted on shafts 456 and 457, respectively, and the gear teeth of each said gear 431 and 432 are in mesh with the teeth of gear 430 which is fixed to shaft 458. In addition to gear 430, two notched ratchets 459 and 460, Fig. 31, are also

ixed to shaft 458 which rotates constantly because either low speed friction clutch 450 or high speed friction clutch 451 is engaged at all times. Loosely mounted on shaft 458 are the driven ratchet space clutch elements comprising two large toothed ratchets 461, 462 connected for short relative movement with the latter connected by a hub to the driven gear 463 which mesh with a gear 464 fastened to shaft 436 for driving the chains.

The manner of operation of the low speed operating mechanism 450, Fig. 30, which is described immediately hereinafter is similar to that of the high speed clutch operating mechanism and said description will apply to both said mechanisms.

As shown in Fig. 30, the clutch operating mechanism consists primarily of a fixed but slideable operating face cam 465, a rotary operating face cam 466, a number of steel balls 467 between the said cams 465 and 466, and three pressure pins 468 which are located between cam 465 and friction clutch gear 432. The uneven annular cam faces of cams 465 and 466 are such that a predetermined turning movement of cam 466 relative to cam 465, backed up by thrust bearing 469, causes an axial movement of cam 465 downward. Said axial movement is imparted to friction clutch discs 454 by means of pressure pins 468, and is sufficient to engage friction clutch 450. Retaining pin 470 which is fixed to frame 423 prevents any rotating movement by cam 465. The cam turning movement is imparted to cam 466, Fig. 31, by arm 472 fastened thereto.

A link 473 connects the extended end of lever arm 172 to the extended end of another lever arm 136 which is used to operate the high speed clutch operating mechanism 451. Thus, a predetermined turning movement imparted to lever arm 136 will actuate the high speed clutch operating mechanism, and thereby cause the high speed friction clutch 451 to engage. The two clutch operating cam mechanisms are relatively positioned so that while the low speed clutch 450 is engaged due to the actuated cams of the low speed clutch operating mechanism, the high speed clutch operating mechanism is ineffective and permits the high speed clutch 451 to remain disengaged, and vice versa; i. e., as shown in Fig. 31, during the time that link 473 is in the position at the right so as to rotate lever arms 472 and 136 in a clockwise direction, the low speed clutch 450 is engaged and the high speed clutch 451 is disengaged; whereas, during the time that link 473 is forced over and latched to the left so as to rotate lever arms 472 and 136 in a counterclockwise direction, the high speed clutch 451 is engaged and the low speed clutch 450 is disengaged. Thus, one or the other of the two friction clutches, 450 or 451, is engaged at all times and through gear 432 or 131, Fig. 28, and pinion 430, the shaft 458, Fig. 31, is rotated continuously at one speed or the other.

In either condition of slow speed operation or high speed operation, the drive is conducted beyond the friction clutches through the cooperation of the clutch gears with pinion 430 fastened to the shaft 458 at the other end of which is a drive ratchet 459 as shown in Fig. 31. This ratchet 459 is part of another clutch which controls the exact extent of feed motion and the timing of the feed motion to be imparted to the document and the feed control tape TP. This feed control clutch FC is controlled by a magnet LS which is impulsed to provide short line space movements of single, double, or triple motions, or energized over longer periods to provide connection for space skipping operations. Before describing the driving connections beyond the feed clutch, it is believed advisable to point out the constructional features of the clutch.

Fixed on shaft 458, Fig. 31, is the ratchet wheel 459 (also see Figs. 3a and 30) which is the drive element of the feed clutch. The driven portion of this clutch includes a sleeve 464 rotatably mounted upon the shaft 75

458. Sleeve 464 is formed with the gear 463 meshed with the gear 464 on the shaft 436 that carries the drive to the tape and record feed devices. Fixed on sleeve 464 is the toothed disk 462. Positioned between disk 462 and ratchet wheel 459 and freely mounted on sleeve 464 is the other toothed disk 461. Disks 461 and 462 are of the same diameter and provided with the same number of oppositely facing teeth. Projecting from disk 462, Fig. 31, and passing with appreciable play through an elongated slot in disk 461 is the pivot stud of a clutch dog 94. The clutch dog 94 lies in front on the disk 461 and has a tooth engaging the driving ratchet 459. The tail of the clutch dog is notched at the free end which is in engagement with a pin extending from the disk 461. A spring 475 tends to rock the clutch dog 94 into engagement with ratchet 459. Another spring 476 is anchored at opposite ends to studs of disks 461 and 462 respectively. Springs 475 and 476 urge the disk 461 to turn clockwise relative to disk 462, such relative movement, when permitted, being limited by the play of the hub of the clutch dog in the notch of the disk 461. The clockwise movement of disk 461 relative to disk 462 is prevented in the declutched positions of the parts (Fig. 31) by a latch 97 engaged with a tooth on disk 461. Latch 97 carries the armature of the feed clutch magnet LS and is urged to latching position by a spring 477. A rebound preventing pawl 478 pivoted on a stud 479 is urged clockwise, Fig. 31, by a spring 480 against the teeth of disk 462 and is constantly maintained effective to prevent reverse movement of the disks 461 and 462.

To effect clutch engagement, magnet LS is energized, withdrawing latch 97 from disk 461. Springs 475 and 476 now act to turn disk 461 clockwise relative to disk 462 and by reason of the pivotal engagement between the disk 461 and the tail of the clutch dog 94 and under the further direct push of the spring 475, the dog is rocked into engagement with the constantly rotating ratchet 459. Clockwise rotation of the ratchet now is transmitted to disk 462 and through springs 475 and 476 to the disk 461. Sleeve 464 rotates clockwise with disk 462 and through gears 463 and 464 rotates the tape feed and sheet feed devices. During rotation of the disks 461 and 462, their teeth are out of normal alignment, disk 461 having been moved clockwise a limited extent relative to disk 462 upon release of the disks by the latch 97. Deenergization of magnet LS to effect clutch disengagement is timed to occur just before a tooth of disk 461 reaches the latch position. Thus, latch 97 will first encounter a tooth of disk 461 and arrest it while disk 462 continues to turn until a tooth thereof is slightly beyond the latch 478. While the disk 462 is moving clockwise relative to the arrested disk 461, the clutch dog 94 is generally withdrawn from ratchet 459 and is rocked free of the ratchet by the time the disk 462 is latched.

Associated with the spacing control magnet LS is a pair of contacts 121 which are closed only when record feeding is in progress and that is when the tape sensing brushes should be effective. These contacts 121 are mounted on insulation spacers and assembled in the machine on the bracket 482 fastened to frame 423 as the carrier of magnet LS. The contacts are operated by an insulation rod 483 fastened to the upper end of the armature latch 97. Whenever magnet LS is energized to cause connection of the feed clutch, armature latch 97 is pulled downward and in so doing pushes the rod 483 down also, whereupon, near the end of the armature stroke, the contacts 121 are closed. Since the contacts are open when the feed devices are at rest, they prevent the reading of a tape stop perforation in the event that some brush strands should protrude through the tape.

A detent 484 is mounted on disk 462 much the same as clutch dog 94. It is also held out normally by a pin on disk 461. When the spacing magnet is operated to make dog 94 effective the same relative movement of

disks 461, 462 causes detent to rock inward and engage a tooth on the oppositely facing ratchet 460 and thus lock all parts against overthrow.

Alongside ratchet 459 is a thin similarly shaped ratchet 485 which is merely a shroud to prevent the point of dog 94 from engaging a point of a tooth on ratchet 459. A loop spring 486 permits short amount of play between 459 and 485.

For long feed operations such as the ejection of a document over and away from the platen, the line space magnet LS is energized along with other controls in order to connect the parts within clutch FC which is situated intermediate the speed change clutches and the sprocket drive shaft. Concurrent therewith is the energization of an eject or fast speed securing magnet FSS, Fig. 31, and a fast speed trip coil FST, Figs. 28 and 29. The latter is normally deenergized and the armature 487 is seen then to hold a clutch 134 ineffective to drive shaft 488. The clutch 134 is of the kind already noted with an inner coil spring which grasps two abutting sleeves when released. The driving part of clutch 134 includes a gear 489 on drive shaft 422, said gear meshing with a gear 490 fastened to the constantly rotating sleeve portion of clutch 134. When magnet FST is energized, armature 487 allows release of the inner spring to grasp the two sleeve ends and connect gear 490 with shaft 488. On the outer end of shaft 488 is the cam 135 for operating to a shift for high speed. The high speed magnet coil FST is pulsed once in order to permit cam 135 to complete one revolution. In so doing, the high lobe of cam 135, Fig. 31, operates against a cam follower lever 491 which moves link 473 to the left. Said movement by link 473 rotates the lever arms 136 and 472 in a counterclockwise direction which causes the low speed clutch operating mechanism to become ineffective and the high speed clutch operating mechanism to become operative, as described hereinbefore. Lever 491 is pivoted at 492 and has a lower extension with a pin 493 for operating the armature 97 so that the clutch FC is held engaged throughout the ejecting operation.

The eject magnet coil FSS remains energized in order to maintain link 473 in the shifted position toward the left. This is accomplished by the engagement of the extended end of armature 138 with the extended end of lever arm 136.

The eject magnet coil FSS is deenergized when one of the carriage tape control brushes EB6—EB10, Fig. 34a, senses a tape "slow down" or "early" perforation such as Et which is seven line spaces in advance of the related tape "stop" perforation 1t. When coil FSS, Fig. 31, is deenergized, the extended end of lever arm 136 disengages from the extended end of spring drawn armature 138. Immediately thereafter, spring 131 returns link 473 and lever arms 136 and 472 to their home positions so as to disengage the high speed clutch 451 and engage the low speed clutch 450. When the tape "stop" perforation is sensed by the carriage control brush, space control magnet LS is deenergized in order to stop the ejecting operation.

It is noted that the deenergization of coil FSS seven line spaces in advance of the "stop" perforation results in the deceleration of the carriage shaft 458 and thereby permits the notched disc 461 to latch at low speed.

Provisions are made for hand operation of the feeding devices. A stud 495 (Fig. 23) extends from frame 29 and has pivoted thereon a gear 496 formed with a collar 497. The latter is fitted with two pins 498 which protrude toward the stud 495 and provide a means of rotating the gear and collar 497. The gear 496 of assembly 497 meshes with gear 499 fastened to a shaft 500 journalled in front frame 29 and feed frame 25. Gear 499 meshes with a gear 501 fastened to shaft 132 which is remembered, Fig. 19, as geared to all other feed shafts. An index plate 502, Fig. 23, is suitably fastened to gear 499 and is visible through a slot in feed frame 25. A

pointer 503 fastened to frame 25 is provided as a reference point for the index.

At the top of the machine, Fig. 12, there is situated the stacker mechanism ST for receiving the sheets or envelopes as they leave the platen and as they are brought upward and around and down behind the top sprockets 13 by the chains C. A sheet is allowed to stay on said chains until it assumes a vertical position above the stacker bedplate 505. When in this position the clips CS holding the sheet are automatically released and the sheet remains in the stacker while the chains continue to advance over the closed path.

The stacker bedplate 505, Fig. 12, is fastened to the main frame 22 and a bracket 506 thereon is fastened to the other main frame 23.

However, before the sheet reaches the rear it must be centrally supported between the chains at the front. Fastened to front and rear chain frames 76 and 77, Fig. 3, are stiffener brackets 520 and 521. Fastened in front 20 of chain frame 76 and extending through the other frame 77 is a guide bar 522. Pivoted mounted on stiffener brackets 520 and 521 are links 523 and 524. A block 525 slidably mounted on bar 522 has pivotally mounted thereon a link 526 which connects links 523 and 524. 25 Fastened to block 525 is a formed sheet guide 527 which is of an inverted U shaped contour, Fig. 12, and extends upwardly from tube 68, and semicircularly aligned with sprockets 13 at the top, and then down below bedplate 505. When chain frame 77 is adjusted for various widths 30 of documents the formed sheet guide 527, Fig. 3, is maintained centralized an equal distance between the chain frames by the link arrangement mentioned.

Formed sheet guide 527 contains a rear slot 528 in which is slidably mounted upper and lower pressure friction mechanisms 529 and 530, Fig. 12. The upper friction mechanism is adjustable between the documents D and the rear face of guide 527 and comprises a flat friction spring 531, a kicker spring 532, mounting bracket 533 and a clip 534. The springs are fastened near the top of 40 bracket 533. The friction mechanism is adjustable for various size documents and applies correct pressure for proper stacking between the documents and the support plate 535. The lower friction mechanism 530 is likewise slidably mounted in slot 528. The lower friction mechanism comprises a friction spring 536, a bracket 537, a clip 538 and a micro switch 539. Friction spring 536 is formed with a tail 540 that contacts the plunger of the micro switch SAC when the amount of spacing between the support plate 535 and the formed paper guide 527 approaches a width inadequate for proper stacking. When the plunger of micro switch SAC is actuated the stacker control magnet SCM, Fig. 4, is energized and armature 541 releases the interior spring clutch 542 to effect a driving connection between pulley 49 and the stacker adjust screw 543. By means of mechanism about to be described the support plate 535 is automatically moved away from the formed sheet guide 527 by screw 543 to permit proper stacking to continue.

The stacker mechanism comprises a rod 544, Fig. 4, 60 fastened in blocks 539 secured to the rear main frame 23. A casting 545 slidably mounted on rod 544 is positioned by track 546, Fig. 5. Fastened in casting 545 is hollow shaft 547 which supports back plates 535. Back plates 535 are clamped on hollow shaft 547 by clamping levers 549. Back plates 535 may be shifted on hollow shaft 547 to provide proper support for any width document being printed. The worm screw shaft 543 is rotatably mounted in blocks 548 and 550 fastened to rear main frame 23. Worm shaft 543 is driven by pulley 65 49 through the spring clutch 542 of well known design. When armature 541 of magnet coil SCM is attracted, worm shaft 543 is allowed to make one revolution. A worm gear 555, Fig. 5, rotatably mounted on a shaft 556 journalled within hollow shaft 547, meshes with the worm shaft 543. Gear 555 is usually held from rotation by

friction so that the motion imparted by worm 543 is motion of translation rather than motion of rotation. shaft 556 is supported by bracket 557, bushing 558 and nob 559. Fastened to shaft 556 is a collar 560 containing a pin 561. Pin 561 is held in a recess in gear 55 by a compression spring 563 coacting between bushing 558 and collar 560. Thus, the gear is keyed to the friction pressure collar. The stacker mechanism may be rapidly relocated by pulling out knob 559 thereby disengaging pin 561 from gear 555. The stacker mechanism is moved downward by the above mechanism each time worm shaft 543 is rotated until the stacker mechanism operates a switch 564, Fig. 4. Switch 564 stops the printing transcriber when the stacker is full of documents.

The sheets or envelopes are drawn positively to and away from the platen P, Fig. 2, with a smooth, graduated but fast motion so that the sheets are not torn even at relatively high speeds of ejection and space skipping between printing impressions.

Returning now to consideration of the synchronized drive to both the record sheet and the feed control tape, it is noted in Fig. 3a that square shaft S, for communicating the drive from the two speed clutch to the feed chains C, also carries the extending shaft 387 connected to the drum 231 which serves not only as a contact drum or the tape brushes but also as a pin feed wheel with pins extending to engage with the central progression of feed perforations 126, Fig. 34a, in the tape TP.

Pivotedly mounted on stud 127, Fig. 1, extending from the feed unit frame 22, is the brush holder 128. A spring tends to swing holder 128 in a counterclockwise direction and press the brushes B1—5, etc., in cooperation with the tape and also keep the tape taut. An adjustable arm 72 is provided with a tape guide roller 6 and is adapted to receive tape loops of varying lengths. Fastened to the shaft 132, Fig. 17a, which also carries the drive gear 131, is a series of cams 133 for separately operating several contacts VF1, VF2, etc., mounted in a holder attached to cross bar 32. Such contacts are used by the feed device to originate control pulses from within the document carriage. The style of operation, as disclosed hereinafter, is that wherein the control impulses of the feeder, in the main, originate in the tabulator and go into the feeder relays, tubes and magnets to effect spacing as determined by the record cards. However, as shown in Fig. 17a, the constantly running cams 133 are effective to close contacts VF1, etc. at relatively slow speed to cause any regular sequence of self controlled feeding operation of line spacing or space skipping alone or in combination by the impulsing of magnet LS alone or magnets LS and FST along with magnet FSS for long feed operations at graduated speeds.

Although the typebar T, Fig. 1, is shown as part of a cooperating tabulator printing mechanism, it is obvious that other forms of printers may be coordinated with the present feed devices which are suited to be wheeled into place and hooked onto a printer with the platen properly placed. Then, by properly timed impulses to the electrical controls LS, FSS, and FST, coordination of printing and sheet feeding is accomplished.

As an example of the record controlled tabulator, the view in Fig. 32 is illustrative. There it is seen that a magazine is at the right and holds a stack of the usual form of tabulating record cards C, and a picker mechanism PC is provided to issue the cards in succession and feed them past the four sensing stations RBa, RB1, RB2 and RB3. This is all explained at length in the aforementioned Patent No. 2,687,087 and it is sufficient to note here that the cards bear data, group number and special X perforations, the latter usually distinguishing heading cards from detail cards. A change from heading to detail cards, and vice versa is often used as a control from X to no X, or no X to X as an initiating control for the sheet feeding devices.

Another form of control is exercised by group control

devices in distinguishing changes in group numbers between successive cards. It is usual that one or more total taking operations are initiated thereby and that the feeding devices are also impelled for skipping to a predetermined line or spacing to separate totals from items.

A certain column of record cards may be set aside for digit perforations to control record feeding. Such perforations are read through a digit commutator and plugged to the desired tape feed control for spacing or skipping.

Associated with the card feeding devices of Fig. 32 are cam contacts CR and CB operated, respectively, by shaft 139 which is constantly turning, and shaft 140 which turns only on card feeding operations. Thus "all cycle" and "card cycle" impulses are provided for use by plugging to control the sheet feeding devices through the tape sensing means in said devices.

Card levers CL1 and CL2, Fig. 32, are operated by passage of the cards C and indicative of the condition of the tabulator to control the feed devices by contacts

such as the card controlled contacts CI. These contacts are illustrative of a form of control which at times includes relays picked up through such contacts and held to determine when a first card is in and when the last card is out.

In addition to the patent application of the Crowell tabulating machine referred to hereinbefore, reference may be made to the Mills et al. Patent No. 2,531,885 and the patent of E. J. Rabenda No. 2,569,829, for further details of the group control devices, heading card control, program control, multiple line printing controls and other controls originating within the tabulator but productive of impulses which may be used selectively to control the spacing or long feed skipping operations of the document feeding devices.

It is noted in Fig. 34b that the double space, triple space, "skip to 1," "skip to 2," etc. are all pluggable to receive the control impulses from the tabulator. They take precedence over each other in the order mentioned. The "skip to" controls refer to the tape brushes, so that

when the "skip to 5" control is plugged it means that the fifth tape brush is to sense a tape perforation in the fifth tape channel and that is where the tape and sheet is to stop, skipping all other intervening controls. The impulse to any of the pluggable sockets can come from any of tabulator sources of group change unequal impulse, x no x , digit selection, all cycles or card cycles, as already mentioned. Before explaining the various feed control circuits it is believed well to point out more about the tape sensing arrangement.

In Figs. 1 and 34a, it is seen that the feed control tape TP is an endless paper band which is advanced by the pin feed contact drum 231. Cooperating with the tape is a line of twelve sensing brushes of which ten are for stopping control, brush B11 is an interlock release analyzer and brush B12 is an overflow sensing control. Of the ten stopping controls, five brushes EB6-EB10 are set aside to sense advanced tape perforations such as the early indicium Et (which is seven spaces advanced beyond the related stop perforation 1t). These early brushes are used to carry impulses to cause the two speed feeding clutch controls to shift back from high to slow speed before the stop at the end of an ejection or a skip.

The other five stop brushes B1-B5 are related, respectively, to early brushes EB6-EB10, and serve instead to sense tape perforations such as 1t or 2t and carry impulses to stop controls for effecting a definite stop of the tape and the connected record sheet or envelope in predetermined positions. The sheet ejection or skip starts wherever dictated by a control impulse from the tabulator and that is determined by the number of lines of a heading, the number of items of an account, the desire to separate headings, the desire to separate parts of an account, or any of the record controlled impulses mentioned hereinbefore. Line spacing is usually carried on independently of the tape perforations;

75

i. e., one or more short impulses to space clutch magnet LS effects short advances of the record. It is ordinarily for advances for four or more spaces that a pair of skip stop perforations are put in the tape to determine where a heading is to start, where item impressions are to start, or where total impressions are to be placed.

Brush B11 is used as a control to determine where it is not necessary to suspend card feeding of the tabulator while an overflow skip or heading area skip is proceeding to the control of perforation 17 of tape channel 1. The tape is punched with perforation 11t to effect the interlock control release when a skip is not a long one; i. e., not a long one such as that of an overflow skip over a long letter head spacing on a sheet top. Perforation 11t is placed 4" in advance of the stop perforation 1t of channel 1, and where it follows the overflow perforation 12t the interlock is not released in time because it is more than the allowable 4" of sheet feed between successive card feed cycles. Since sheet length is limited to 12" the interlock controls are also arranged to allow feeding sheets without interlocking if the first printed line is from a multiple line MLR card.

When there are too many related items to fit on one sheet it is necessary to put the overflow items on a second sheet. In such cases, brush B12 in cooperation with tape perforation 12t determines where the overflow skip is to start. Any predetermined position can be selected as the last line of a form and the tape punched in the twelfth channel at the corresponding position to initiate overflow skipping.

The feed devices operate at two speeds, fast speed (60" per second) for skips of 7 or more spaces, and slow speed (12" per second) for line spacing or skips of less than 7 spaces. For skips longer than 7 spaces the feed is started at slow speed, changed to fast speed, and changed back to slow speed 7 spaces before stopping, so that the feed is continuous and with gradual acceleration and deceleration as a harmonic motion without abrupt change to high speed and back to slow speed. The shift to high speed is automatic and invariable on skips of more than 7 spaces, but the shift back to slow speed is tape controlled through an early brush which is impaled 7 spaces before the stop perforation calls for a definite end to the record advance.

A single space control is the normal operation and will take place invariably unless the feed controls are signalled otherwise. Double and triple space control takes precedence over single space control. All ejection and skip controls take precedence over spacing control and a higher order skip takes precedence over a lower order skip.

At the top of Fig. 34b is shown the power source PS and the main lines 150 and 151. Other lines and wires are connected to the voltage divider VD for the different desired levels of electrical potential. The carriage motor M is effective through switch SW and runs continuously while the tabulator and feed unit are in operation. Other motor switch controls (not shown) are provided to stop the machine if the covers are removed, or if the magazine is empty or if the stacker is full.

As the first example of a feed control circuit, the case of an ordinary line spacing operation will be considered. As an accompaniment to every printing operation it is desired to effect controls for line spacing the record sheet and also for advancing the feed control tape to be adjusted in synchronism therewith. All tabulator cycles are considered as list cycles unless a "non print" control is called for, and therefore, the feed devices will operate on every cycle unless the "space suppress" control is called into play.

Assuming an ordinary list cycle, then the cam contacts CR1, Fig. 34a, are closed early in the cycle and the feed clutch magnet LS is energized by the following

circuit for a single line space: starting with the 40 volt line 155, Fig. 34b, and continuing through cam contacts CR1, Fig. 34a, normally closed space controlled contacts AS5a (shifted when "all skips" control of spacing is initiated), closed "1st card" contacts C1a (a form of card lever control insuring that a first card is sufficiently advanced in the tabulator), normally closed space suppression contacts SSc, tube TH16 which is a thyratron of the type of a 2D21 and which is fired through wire 154. Since the line space magnet LS is wired in the plate circuit of the tube TH16 it is energized by an impulse through the tube and wire 156 of 130 volt potential. Magnet LS is energized but momentarily until knocked down by the activation of a stop relay, but it is sustained long enough to engage the clutch pawl 94, Fig. 31, for one step of motion of the feed clutch which motion is equivalent to a line space advance on the record sheet.

As soon as the line space armature 97 is attracted to permit spacing, the associated contacts 121, Fig. 31, are closed immediately upon the start of spacing. In order to allow only a single space of motion, the contacts 121, Fig. 34a, are effective at once to pick up a stop relay SR and also fire a tube TH14 which extinguishes the line space tube TH16. The stop relay circuit is closed as follows: line 155, normally closed restore relay contacts REb, "skip to 1" normally closed contacts S1b, and then successively through the other normally closed "skip to" contacts S2b, S3b, S4b and S5b, wire 163, the line space armature contact 121, wire 165, tube TH14 which is fired over wire 154 and makes effective its plate circuit with stop relay SR, either cam contacts CR7 or normally closed skip stop contacts SKSb, and line 156. At the same time a pulse is transmitted through the capacitor C8 to extinguish the tube TH16, thereby deenergizing the connected line space magnet LS and the feed clutch is again disconnected after the record sheet has moved only a single line space.

The reason that the firing of tube TH14 extinguishes tube TH16 is as follows:

When tube TH16 is conducting and before tube TH14 conducts, the potential at the plate of tube TH16 is about plus 10 volts and at the plate of tube TH14 is plus 130 volts. This is assuming a ten volt tube drop in tube TH16 and a 110 volt drop across the line space magnet LS. When tube TH14 fires, the potential at the plate of this tube drops from plus 130 volts to plus 10 volts. Because of the capacitive coupling C8 between the plates of tubes TH14 and TH16, this drop of potential appears momentarily at the plate of tube TH16 forcing it to a potential of approximately minus 120 volts. This drops the plate potential below cathode potential which is zero potential and the tube shuts off. This circuit may flip both ways; in other words, tube TH16 may extinguish tube TH14 and vice versa.

It was noted that at the time that the line space magnet LS was deenergized that the stop relay SR was picked up. This relay is effective, as shown in Fig. 34b, to close a pair of contacts SRa and SRb in series with pickup and hold coils of a skip stop control relay SKS. The pickup circuit for this control relay includes line 151, cam contacts CRA, relay contacts SRb, the pickup coil of relay SKS and line 150. The hold circuit passes through line 151, relay contacts SRa, relay contacts SKSa, the hold coil SKS and line 150. The skip stop relay SKS is then effective to open contacts SKSb, Fig. 34b, to break the circuit to the stop relay SR with the cam contacts CR7 open.

When double or triple line spacing movements are required, the line space magnet LS is given additional impulses through extra cam contact wiring prepared by relays under control of the tabulator. Referring to the upper right hand side of Fig. 34b, it is seen that a double space relay DSA has a pickup coil wired in series with

plug socket 167. It is to this socket that a direct card control from the card sensing brush CB1, Fig. 32, may be effected by direct plugging, or any of the tabulator impulse emitting connections such as "all cycles" impulses, card cycle" impulses, group change impulses, etc., may be connected to energize the double space controls whenever the related printing impressions are to be set out by extra spacing. When the double space pickup coil DSA is energized it establishes connections to an associated holding coil through the closure of connected contacts SSA_a and the complete pickup circuit involves line 151, Fig. 34b, wires 160 and 161, cam contacts CRC, relay contacts DSA_a, the second pickup coil of relay DS and a wire to line 150. The holding circuit for the relay includes somewhat similar connections through cam contacts CRB, relay contacts DS_b, the holding coil of the relay DS and line 150.

Turning to Fig. 34a, it is seen that the double space relay DS closes contacts DSc in series with cam contacts CR2 and the line space magnet LS to effect a second impulse therefrom over connections including wire 155, cam contacts CR2, relay contacts DSc, "first card in" contacts Cl_a, normally closed space suppression contacts Sc, tube TH16 which when made conductive carries the circuit further through line space magnet LS and wire 156 to the line. When magnet LS is thus energized for the second time, it permits one step of the feed clutch and also operates to close the armature contacts 121 in series with tube TH14, and it is through such connections that the line space clutching operation is terminated to limit the strip advance to just a single second step of movement as described fully hereinbefore.

In the event that a triple line space is desired, then lug connections are made to the socket 168, Fig. 34b, in series with the triple space control relay TSA. This relay also has pickup and holding connections through cam contacts CRC and CRB as already traced in connection with the double space control. Triple space relay TS is shown near the bottom of Fig. 34a to exercise control over two contacts TSc and TSd connected respectively to cam contacts CR2 and CR3 which are in series with the line space control tube TH16. When these contacts are closed by the demand for a triple space as initiated by the energization of magnet TSA, three impulses are imparted successively to the line space control magnet LS through cam contacts CR1, CR2 and CR3 over the circuit described hereinbefore.

In the event that a certain tabulator operation is to be free of record sheet advance control, such as in the case of non-printing operations, then a space suppression control is called into action to prevent operation of any of the feed clutch controls of the carriage. A plug connection is made to socket 169, Fig. 34b, to carry such a space suppression control impulse through a pickup coil of a space suppression relay SSA. This relay SSA has other pickup and hold coils wired to cam contacts CRC and CRB similar to the connections already described for relays DS and TS. In addition thereto relay SS is subject to being picked up by the closure of non-print contacts NPa from another tabulator control.

When space suppression relay SS is made effective it serves to open contact SSC, Fig. 34a, which has been noted hereinbefore as one of the series connections making possible the spacing circuits through the line space control to tube TH16. Whenever relay SS is energized, the spacing circuit is made ineffective and tabulator cycles may be performed without an accompanying sheet feed operation.

Regarding space skipping operations; i. e., operations calling for a sheet ejection or advance by selection of one or the other of five tape sensing controls at the top of Fig. 34a, it is noted that the five tape brushes B1-B5 cooperate with different channels of the tape TP and it is through the differential spacing of tape perforations cooperating therewith that a choice may be made of the

extent of feed according to various tabulating operations and according to the direction of the plugging therefrom to the five places.

Referring to the center of Fig. 34b it is seen that a series of five "skip to" relays S1-S5 are wired with separate plug sockets such as 170 to make them individually receptive to any of the already identified impulses from the tabulator to select the desired extent of sheet feeding to go with particular areas of printing. Assuming, for example, that the shortest and first skip feeding control is the one desired, then the plugging will be to socket 170 (from a card brush RB_i, Fig. 32, for example, for direct card control) and the relay S1, Fig. 34b, is picked up by connections including the "first card in" contacts Cl_b, cam contacts CRD and line 150. A holding circuit is established for relay S1 by the closure of relay contacts S1_a, and the complete circuit includes line 151, cam contacts CRE, card contacts Cl_c, wire 171, relay contacts S1_a, holding coil S1 and line 150. A relay R8 is picked up through CR27, S1-2 points, pickup coil relay B and line 150. The hold of relay 8 is through CR29 or skip contacts SKSc, card contacts 1e, wire 162, relay contacts R8-1, holding coil R8 and line 150.

Relay S1 then serves to operate contacts in several places concerned with the selection of the extent of record feeding. However, the primary purpose of the relay is to select the first and sixth tape sensing brushes B1 and EB6 as effective to cause speed shifting and stopping control.

Along with the selection of any "skip to" control there is made effective an "all skips" relay AS, Fig. 34b, which is seen to be wired to be picked up by the circuit through line 151, cam contacts CR22, card contacts Cl_c, any of the skip to contacts R8-2, S2h-S5h, the pickup coil of relay AS and line 150. A hold circuit is established through contacts AS_a. Other contacts such as contacts AS_b, Fig. 34a, are in circuits involving skipping.

Whenever a skip or eject of sheet or envelope is called for, the line space magnet LS is energized by the closure of cam contacts CR1 the same as for spacing. However, magnet LS is not immediately deenergized by the closure of related contacts 121 as in spacing. This continuance of feeding is caused by the opening of one of the normally closed "skip to" contacts such as contacts S1_b in series with contacts 121 and the disengage control tube TH14. As a result the feed clutch is engaged and permitted to remain engaged for the full long feed.

If the skip is to be greater than 7 line spaces, then the "early brush" controls are ineffective at the beginning of the skip cycle and the fast speed securing magnet FSS is energized for use later when the trip magnet FST picks out the time for the speed change as already explained in connection with Figs. 29 and 31. A sample circuit for energizing magnet FSS includes wire 155, Fig. 34a, cam contacts CR5, the various normally closed "skip to" contacts S5d, S4d, S3d and S2d, contacts S1d now closed by relay S1, "early brush" relay contacts ER1a normally closed, wires 173 and 174, tube TH15, magnet FSS and wire 156 to the power source. Magnet FSS is not immediately effective because the latching of its armature 138 is delayed until the related fast speed magnet FST is operated to trip the shift clutch and operate the cam for changing the position of the two speed clutch linkage from slow to fast and lower arm 136 and catch it under armature 138.

At the beginning of the skip movement, when the feed clutch is tripped by magnet LS, the advance is at slow speed because of the normal arrangement of the two speed clutch 2SC, Figs. 28-31. However, at 10° when cam contacts CR6 close, the fast speed side of the clutch is called into action by the energization of the fast speed trip magnet FST by a circuit which involves wire 154, cam contacts CR6, "all skips" contacts AS_b, magnet FST and wire 156. Magnet FST then releases clutch 134, Fig. 28, which is the operator for cam 135 operating on the linkage

to effect a shift of the friction clutch effect to the high speed side of clutch 2SC.

When an early perforation Et is sensed for the "skip to 1" control for channel 1 (i. e., by the related EB6 brush of channel 6) then the feed speed controls are shifted back to slow speed as result of the following circuit. Wire 155, Fig. 34a, common brush B13, contact drum 231, a hole Et in tape TP, brush EB6, wire 175 (a branch circuit through tube TH6 to pick up early relay ER1), another branch through normally open "skip to 1" contacts S1c now closed, normally closed contacts S2c, S3c, S4c, and S5c, wire 172, tube TH13 and wire 156. When tube TH13 is fired it serves to extinguish the related coupled tube TH15, thus deenergizing the fast speed solenoid FSS. As a result, Fig. 31, the armature 138 is released and the spring 131 becomes effective to shift the speed clutch back to the slow speed drive.

The early brush relay ER1 is sustained by a hold circuit shown in Fig. 34b, said circuit including line 151, cam contacts CRE, card contacts C1c, relay contacts ER1c, relay ER1 and line 150.

So far, the ejection skipping operation has involved first, the action of the feed magnet LS to start the feed, and then temporary use of the magnets FSS and FST to shift into and out of high speed control. Now, the next step is to deenergize the feed magnet LS to stop the record at the selected "skip to 1" position.

As the tape TP continues to advance with the perforation Et going beyond brush EB6, the related stop perforation 1t eventually comes under stop brush B1 and a circuit is completed to the stop relay SR, and the feed magnet LS is deenergized because of this circuit which is as follows: wire 155, Fig. 34a, common brush B13, contact drum 231, stop perforation 1t in tape TP, stop brush B1, and then in two directions, one of which involves tube TH1 and stop brush magnet SB, and the other of which includes the "skip to" contacts S1b, and then in series through the successive contacts S2b, S3b, S4b and S5b, wire 163, armature contact 121, wire 165, tube TH14, relay SR, cam contacts CR7 and wire 156. As a result of the firing of tube TH14, the coupled tube TH16 shuts off and connected magnet LS is deenergized. In Fig. 31 it is seen that deenergization of magnet LS causes declutching of the feed clutch with the result that the record sheet is stopped in a position agreeing with the position of the tape stop perforation 1t. If the ejection skip to channel 1 had been less than 7 line spaces, then the early brush relay ER1 would have been picked up early and opened contacts ER1a to prevent the magnet FSS from becoming energized to latch at high speed.

Although tape channels 1 and 6 are considered in the example given, it is apparent that other pairs of channels and early and stop brushes work in a similar fashion for skips to lower form positions.

As mentioned hereinbefore, the eleventh channel of the tape is sensed to determine whether the anticipated feed to channel 1 is less than 4 inches and if so to disable the tabulator feed interlock so that card feeding is not suspended. For this control the tape TP is perforated in channel 11 four inches in advance of the stop perforation 1t of channel 1. When the channel 11 interlock perforation is sensed prior to the channel 1 skip, a circuit is established through brush B11, tube TH11, stop brush contacts SBb and interlock relay IR. The relay IR is then effective in the tabulator as an interlock release until deenergized by the opening of contacts SBb when stop brush B1 senses the stop perforation 1t.

A limit is set up for the number of items which a sheet or envelope is to hold. The overflow tape perforation in channel 12 is usually synchronized with a line near the bottom of the sheet. When the overflow position is reached, Fig. 34a, the tape perforation in channel 12 comes under brush B12 and a circuit is established to tube TH12 and through "all skips" contacts ASC, stop brush contacts SBa, and overflow relay OR. Relay OR is

sustained by energization of its hold coil by the circuit Fig. 34b, including line 151, cam contacts CR29 or skip stop contacts SKSc, card contacts C1e, wire 162, contact ORa, relay OR and line 150. Relay OR also closes contacts ORb in series with cam contacts CRD and lever contacts C1b, and relay contacts SL-5 connected to the "skip to 1" socket 170 to call relay S1 into operation for an overflow eject skip operation.

A series of keys are provided for manual control of the feed devices. As shown near the top of Fig. 34b it is seen that the keys SC, R and ST are connected respectively to close contacts in series with a spacing control magnet SPA, a restoring magnet RE and a stopping control magnet SP.

The key ST is provided as an emergency stop device and will terminate feeding immediately upon being depressed. Stop magnet SP controls two contacts SPt and SPx in series with the stopping control to tubes TH13 and TH14. The first mentioned contact is in a circuit involving line 152, stop contacts SPt, tube TH13 and wire 156. Energization of tube TH13 serves to deenergize the coupled tube TH15 which then controls deenergization of the fast speed solenoid FSS. In the event that a high speed drive is in effect when the stopping control is exercised, then the deenergization of the feed clutch magnet LS is not immediately effected because it is desired to slow down the feed before stopping it altogether. For such slowdown control there is provided the fast engaging contact 123 which is normally closed in series with the stopping contact SPx. However, when the fast speed magnet FS is energized, contacts 123 are opened and only close again after the magnet has been deenergized. Then the stopping circuit is completed as follows: Line 152, contacts SPx, engaging contact 123, wire 165, tube TH14 and stopping relay SR. Energization of tube TH14 causes deenergization of the coupled tube TH16 which in turn causes deenergization of the feed clutch magnet LS and the feeding operation is thereby terminated.

Whenever the spacing control key SC is used, Fig. 34b it causes the energization of the pickup coil of the spacing control relay SPA. A hold circuit is provided for the relay SPA through line 151, cam contacts CRE, card contacts C1C, relay contacts SPAa, relay SPA and line 150. Relay SPA then serves to shift contacts SPAc, Fig. 34a to close a shunt circuit around the card contacts C1a, and to establish an impulsing connection to the line spacing control tube TH16 which is impaled every time cam contacts CR1 close during the time that the spacing control key is held depressed.

The restore key R, Fig. 34b, when depressed causes clutch operation through the action of related relay R1 which not only starts the feed clutch and vacuum feed operating, but also calls into play the tape sensing device for channel 1 to cause the sheet to be brought into the home position. As soon as the pickup coil of relay R1 is energized, the associated contacts REa close and put the spacing control relay SPA in parallel therewith and the spacing operation is initiated by SPAc to activate the feed control magnet LS as already described. The relay RE also closes contacts REb in series with the holding coil to sustain the operation of resetting. Referring to the top of Fig. 34a it is seen that restore relay RE also acts to shift contacts REb to close them in series with the stop brush B1 and normally closed contacts S1b, S2b etc., wire 163, feed contacts 121, wire 165 and tube TH16 which serves to deenergize the feed tube TH16 and at the same time energize the stop relay SR.

The electrical controls for governing the operation of the present machine for advancing separate sheets or envelopes to the printing position are in some respect similar to the controls set forth in the Patent No. 2,684,746 for a continuous form feeding device. There are some differences due to the separate nature of the sheets and envelopes to be fed and also due to the provision of interlock controls so that sheet lengths and skip

machine cycle time. The present specification should so be considered in the light of the disclosure in the application of A. B. Crowell et al., Serial No. 227,672, filed on May 22, 1951, now Patent No. 2,749,839, for a Record Controlled Printing Machine which relates to the transcriber printing mechanism with which the present mechanism and electrical controls are associated. Many of the cam contacts such as those identified CR and many of the control relays are in the printer of the application mentioned. The cam contacts identified with the VF letters are those operated by the sheet feeding device and have been pointed out hereinbefore in connection with the operating mechanism. The relays numbered R375, etc. and the three tubes T609, T601 and T602 are additional relays and tubes provided for the control of the sheet feeding carriage.

Since the length of sheet or envelope is limited to 12" the interlocking circuits between the printer and carriage have been arranged to permit feeding of sheets up to 12" in length without interlocking the machine if the first printed line on the sheet is to be taken from the lower 3" printing unit of the transcriber and the card from which the information is derived is of the kind holding multiple line data. This is possible because the "skip to" impulse is initiated just after performance of second line (B) printing. If the first line of the next document to be performed at "B" line print time, then about twice as much time is available for the skip than if the first line was to be printed at "A" line print time.

A plugging arrangement is provided in accordance with the desired sheet length and if the sheet length is to be more than 4" the interlock controls will operate to delay or suspend operation of the transcriber while the extra length of sheet is being handled. The interlock is arranged to permit steady operation in case of printing the first line of the sheet from the multiple line card as noted above.

When the sheet feeding carriage is properly connected to the transcriber mechanically there is also an automatic connection made electrically by the assembly of the connector plug 178, Fig. 34d, and a circuit is established from line 151 through plug 178 and control relay R378 wired to the other side of the line 150. This relay R378 has a number of control contacts in different parts of the carriage wiring to allow performance only when the carriage is properly assembled to the printer. A somewhat similar switch (not shown) is provided to energize a control relay for the carriage motor to allow it to operate only when two machines are properly assembled and there is closure of the proper switches and covers and the absence of any jammed condition in the feeding path.

The carriage is provided with stopping, spacing and restoring keys ST, SC and R, Fig. 34b, already noted. The stopping and spacing keys provide the controls which the titles imply. The restore key R has a number of other functions which provide more than the return of the tape to a starting position. The restore key is used not only to cause the control tape TP to skip around to the point at which the perforation is sensed in the first channel, but it also at the same time energizes the vacuum clutch controls to cause a sheet to be advanced from the magazine to the gripping clips on the chains. Initially the restoring key is depressed successively until the first sheet arrives at the platen. The same key is also used to clear the final sheet out of the carriage after a corresponding series of tabulator cards have been completely analyzed.

Assuming that the sheet feed carriage is properly connected to the printer and that the plugs and switches are connected, then depression of the restore key R will provide electrical controls for correctly positioning the feeding chains and the gripping clips thereon for reception of the first sheet. When the restoring key R, Fig. 34b, is depressed a circuit is completed from line 151 through wire 169, contacts R, contacts R380-2, normally closed

but opened to prevent holding RE by depressed R key, the pickup coil of relay RE and line 150. Relay RE is held through normally closed interlock relay contacts R380-1 (which open earlier than R382-5) and either stop relay contacts SR-5 or delay relay R382-5 contacts, related contacts REa and line 151. Restore relay RE has contacts RE-2, (Fig. 34d) in series with the pickup coil of a run in delay relay R382 and the latter is energized through the circuit including line 151, wire 179, contacts RE-2, contacts R378-3 now closed, pickup coil R382 and line 150. Relay R382 is held energized by a circuit including the related contact R382-1 and then through either the normally closed contacts R380-3 (which are undisturbed unless an interlock pulse by relay IR breaks them) or related contacts SB-4 closed at the end of a skipping operation to the home position. Relay R382 has control contacts R382-2, Fig. 34e, in series with the tube T600 for controlling the vacuum clutch magnet VCM as noted hereinafter.

Returning to the controls exercised by the restoring relay RE, it is noted that when it is energized, one of its contacts REb, Fig. 34a, arranges a circuit to deenergize the connections to the line space magnet LS when the first channel position is sensed with the perforation It appearing in the home position. Before that happens, the line space magnet is first energized to engage the clutch for operating the chains and the tape feed to rotate and operate all the connections tending to cause the tape to go toward the home position. This is done by means of circuit connections initiated by the closure of REb, Fig. 34b, and pickup of the space magnet SPA. Since the relay RE through its holding coil, Fig. 34b, is held by the closure of relay point R382-5 the related control contacts REb, Fig. 34a, in the carriage line space circuit remain closed until relay R382 is deenergized at the end of the first run in cycle. The cam contacts in the circuit with the line space control tube TH16 prevents the magnet LS from being reenergized after the first run in cycle.

Cooperating with the tape brush B11, Fig. 34a, is the interlock control perforation in the eleventh channel on the tape TP. As this control perforation is sensed when the tape is moved on the restoring cycle, an interlock control relay IR is energized through the brush B11 and connections to tube TH11. Relay IR is a latching type relay wherein the coil just mentioned causes closure of contacts or movement of related contacts accompanied by mechanical latching which is broken down by another latch tripping IR coil shown at the right in Fig. 34d and mentioned hereinafter. When relay IR is energized one of the controls exercised is that associated with the opening of contacts IR-5 shown in Fig. 34e. These contacts are in series with the gripping control magnets HSM in a circuit including wire 176 to the 40 volt line. It will be recalled in connection with the mechanical description that the gripping clips on the chains are opened only when the gripper magnets HSM are deenergized. Therefore, the action just described in connection with the interlock relay IR serves to deenergize magnets HSM to open the gripper fingers and during restoration prepare for the reception of an incoming sheet. The gripper magnets HSM are normally held energized by the circuit mentioned.

As the chains and control tape arrive in the home position, the perforation It on the tape is positioned under the brush B1, Fig. 34a, and a circuit is completed for firing the stopping control tubes TH1 and TH14 which in turn control the energization of stopping control relays SB and SR. These relays operate contacts in various positions for terminating further movement of the chains and tape until the restoring key R is again depressed to pick up relay RE. The one stop control relay SB is held as shown in the circuit of Fig. 34d through the related relay point SB-1 and the interlock contact IR-6

also closed to line 151. It is at this time that the chains are stopped in the proper position with the gripping clips open to receive the first sheet or envelope. With relay SB energized a circuit is completed from the 40 volt line, Fig. 34e, and through the shifted relay contacts SB-5, relay contacts R382-2, to the grid of tube T600 which becomes effective to energize the vacuum feed clutch magnet VCM through cam contacts VF1 and then to the +130 volt line. This causes the controls for the vacuum feed arm to engage and oscillate it to bend out the leading edge of the first sheet in the magazine.

When the relay points SB-5 are transferred to make the vacuum controls operate they also act to open a related contact point which is normally connected through wire 181 to keep the sheet stop magnets SSM normally energized. Transfer of the relay points opens the circuit and deenergizes magnets SSM to allow the paper stops to come into the effective position ready to form an abutment for the leading edge of the incoming sheet.

In addition to the controls for bending the edge of the leading sheet by vacuum and arranging for the stopping position for it, it is also required that the holder of the vacuum arms be oscillated to bring the first sheet into engagement with the continuously rotating feed rolls so that it is advanced out of the magazine and over to the paper stops. This is performed at about 120° of the carriage time. Then a circuit is completed from the +40 volt line, Fig. 34e, through the cam contacts VF-3 to the grid of tube T601 which is then activated to energize the sheet feed magnet SFM and cam contacts VF2 to the +130 volt line. Operation of magnet SFM releases the clutch for activating the oscillating vacuum parts to advance the leading edge of the sheet into the feed rollers.

It will be recalled that when the restore key R was operated the related contacts RE-2, Fig. 34d, were closed in series with the pickup coil of relay R382. When this was done the related relay point R382-4 was opened in series with the connections through tube T602 in series with the other interlock control relay R380. When relay contacts R382-4 opened, the connected condenser allowed the potential on the grid of tube T602 to rise in value enough to fire the tube. The circuit is timed to provide a delay of approximately 1½ seconds. When the tube T602 fires, a circuit is completed through the other relay contacts IR-3 now closed and in series with the pickup coil of relay R380. The hold coil of this relay is shorted to provide a longer drop out time.

The run-in delay controls provide the time which will allow the vacuum feed devices to complete the operation of bringing the sheet to the gripping clips before a second cycle and movement of the chains can be started. It happens with handling the first sheet to the platen and whenever the machine is cleared.

As soon as control relay R380 is energized, the related relay point R380-3, Fig. 34d, is opened to tend to break the holding circuit of relay R382. However, the parallel relay point SB-4 will not open until later in the cycle and therefore the circuit to the holding coil of relay R382 remains effective. At this point in the operation it is desirable that the contacts latched up by the action of interlock relay IR, Fig. 34a, be changed in position by energization of the cooperating latch tripping coil IR shown in Fig. 34d. The circuit includes line 151, wire 177, contacts R380-4 now closed, relay contacts R382-3 still transferred, the latch tripping coil of relay IR and line 150. As soon as the contacts of relay IR are released, the related contacts IR-5 close, Fig. 34e, and reestablish the circuit to the gripper magnets HSM to allow the chain clips to grasp the sheet at a time which is calculated to coincide with the appearance of the leading edge of the sheet at the stops. Since the other relay SB, Fig. 34d, was held by the relay contacts IR-6 and the related contacts SB-1, as soon as the circuit through these points is again broken by the opening of contacts

IR-6, relay SB drops out and the circuit through contact SB-5 is again established to the paper stop magnets SSM so that the abutments are again lifted out of the path of the sheet which is now positioned on the chains. At the same time the opening of relay points SB-4 cuts out the holding circuit to relay R382. When the relay contact R382-5, Fig. 34b open, and since that is accompanied by the open position of relay points SR-5, the circuit to the hold coil of the restore relay RE is opened to condition the escapement tube TH16, Fig. 34a, to fire the carriage line space magnet LS when the restoring key is again depressed.

The restoring key is depressed successively until the first sheet is advanced to the print receiving position on the platen. With the sheet in the printing position the operator next depresses the start key in the printing transcriber. The carriage will advance the sheet on each listing cycle in the usual fashion unless plugged for space suppression. The spacing circuit is the same as that described hereinbefore in connection with the description of the tape controls except that only one or two spaces are used for the second line of print. Single spacing is the normal operation. This is to permit more time for ejecting and closing the gripping clips of the chains on new sheet.

When an incoming sheet reaches the stopping position it is tested for alignment by a pair of sheet sensing levers on either side of the carriage and near the chain engaging positions. These sheet levers cooperate with switches and electrical controls of the kind shown in Fig. 34c for stopping operation of the printer whenever the sheet is at such an angle that either one of the levers alone is operative or there is no contact at all. At the center of Fig. 34c it is seen that the contacts 189 and 199 of the two levers CL1 and CL2 are wired to magnets R455 and R459 respectively. The former is a latching type of relay with a cooperating latching coil in series with normally open contacts SB-4. When the sheet is connected to the chains correctly the two levers close the contacts at the same time energizing relays R458 (parallel with R455) and relay R459 to transfer the related contacts R458-3 and R459-2. Whenever relay R458 is energized, the related relay R455 is also picked up and serves to open the related relay contacts R455-2. The shifted contacts of relay R455 are restored to normal by the associated tripping coil of relay R455 which is energized by the action of contacts SB-4, closed at the end of a ejection cycle.

Near the bottom of Fig. 34c it is seen that the normally closed running circuit of the printing transcriber includes the holding coil of a stop control relay R545 in series with which are the series contacts R458-3 and R459-2 which when operated together preserve the normal energized condition through others of a series of normally closed running contacts such as the stacker stop contact SSS.

When a condition prevails so that the sheet is improperly grasped by the chains and it is in a crooked position which would result in jamming at some point along the path of the chains, then the condition is sensed by the sheet levers and one or the other of the relay contact R458-3 or R459-2 do not transfer and relay R545 is de-energized to stop the machine. When there is a failure of a form or sheet to be presented, then relay R455 is not energized and relay R456 is allowed to be energized through the normally closed points R455-2. This causes the related contacts R456-2 to be opened in the normally closed transcriber running circuit to de-energize relay R-545 to stop the machine. The circuits just mentioned are called into operation to test the running circuit once for each actuating cycle.

As printing occurs, the feed devices continue to line space in the usual manner until such a time as a group change occurs or there is some tabulator control impuls

which is directed into the controls to direct ejection skipping to take place. Then in addition to energizing the line space clutch magnet LS the same impulse is used to operate the vacuum suction arms through the operation of magnet VCM to cause another sheet to come into the feed devices. Going back to the initiation of such a skipping operation it will be started by such a condition as a group change and the usual emission of an unequal impulse. Such an impulse is directed to plugged socket 183, Fig. 34c, and the pickup coil of relay R372 is activated. Relay R372 is then held by a circuit including a line 151, cam contacts CR58, relay contacts R372-1, the holding coil R-372 and the other side of the line 150. Relay R372 then picks up relay OR as follows: line 151, cam contacts CR24, relay contacts R372-2 and the pickup coil of relay OR. The relay OR is held through line 151, Fig. 34b, cam contacts CR29 or relay contacts SKSc, card lever contact Cl, wire 162, contacts ORa, holding coil OR and line 150. Relay OR then serves to pick up the "skip to 1" relay S1 as follows: line 151, Fig. 34b, normally closed relay contacts S1-5, relay contacts ORb now transferred, the pickup coil of relay S1, card lever contacts Clb, cam contacts CRD and line 150. The stopping control relay S1 is held through line 150 and cam contacts CRE, card lever contacts Clc, wire 171, contacts S1a, the hold coil of relay S1 and line 150. Relay S1 then picks up another relay R8 through the closure of contacts S1-2 and a circuit including cam contacts CR27. Relay R8 is held through the same kind of hold circuit already described for relay OR. Relay R8 then serves to pick up the relay AS which is termed "all skips" relay since it is picked up in connection with any of the skipping operations. When the skipping operation is to the first position under control of the first channel of the tape then relay R8 is effective to close contacts R8-2 and the complete pickup circuit includes line 151, cam contacts CR22, card lever contacts Clc, relay contacts R8-2, the pickup coil of relay AS and line 150. Relay AS is then held through the same hold circuit as described in connection with relay R8 and relay OR. It is noted hereinbefore how relay AS operates several of the contacts in series with the feeding controls noted on Fig. 34a.

When skip relay S1 is picked up by an eject skipping operation to stack a printed sheet and bring a new sheet into the feeding unit, then the vacuum feed magnet VCM is also impelled at the third quarter of the operating time of the cycle through a circuit including the +40 volt line 151, Fig. 34e, cam contacts CR82, relay contacts S1-3, a delay unit DU, a plug wire to socket 184 and then to the grid of tube T600 which is activated to energize the vacuum feed clutch VCM, through cam contacts VF1 and the +130 volt line. After the vacuum feed operation has started and picked up a sheet, the other sheet feed clutch magnet SFM is energized through the +40 volt line, cam contacts VF3 and over to the grid of tube T601. The tube is allowed to fire at 120° through the sheet feed magnet SFM and cam contacts VF2 to the +130 volt line. This releases the oscillating roll and the paper sheet is then carried from the vacuum arms over to the gripper fingers which at the time are in an open position to receive the leading edge of the sheet as it is stopped by the paper stops for alignment before the grippers are allowed to close in.

The vacuum feed delay device DU is a mechanically controlled electrical timer for governing the starting time of the vacuum arm pick off and rock toward feed rollers. At printing time when the chains and clips are immovable is the time for gripping an incoming sheet. Therefore, optimum operating conditions are achieved by varying the time of start of vacuum feed so that the sheet arrives at the clips at print time.

As noted hereinbefore, the circuit delay unit DU is provided in the circuit of tube T600. This delay unit is of the commutator type and provided with a circular arrangement of a plurality of contacts which are con-

nected to a control plug panel. Since the center contact arm rotates at a constant speed it is evident that the timing of the impulse to the grid of tube T600 is made selective by plug wiring to one or the other of the contact plugs related to the contacts in an arc, and the circuit is established to cause the tube T600 to fire differentially energizing the vacuum feed magnet VCM at a selected time interval. This delay unit is provided to control the starting point of the vacuum feed for various lengths of sheets or envelopes.

At about 350° in the same cycle, the line space magnet LS, Fig. 34a, is energized through the closure of the related relay contacts AS-5 to start the skipping operation. The skipping operation will be completed at some prior time to 160° if the sheet is of a length less than 4". If the sheet is more than 4" in length but less than 12" then the skip will be completed some time before 340° in a cycle of operation.

When the skipping operation proceeds, the gripping magnets HSM will be deenergized until the interlock release control of the tape in channel 11 is reached and at that time the relay IR will be picked up. The related relay contacts IR-5, Fig. 34e, open to deenergize the gripper magnets HSM, allowing the chain clips to open as the chains come to a halt. Then the stopping control perforation It, Fig. 34a, in channel 1 of the tape fires the stopping control to TH1, and connected relay SB is picked up and the line space magnet LS is deenergized by the deenergizing of the related tube. The paper stop magnets SSM, Fig. 34e, are energized whenever the stop relay SB is deenergized.

At 180° (for a 4" sheet) in the next cycle, relay IR, Fig. 34d, acts to trip the latched contacts, and related relay contact IR-5 closes, Fig. 34e, energizing the gripper magnets HSM. When relay IR is picked up, the hold circuit of stop relay SB, Fig. 34d, is broken by the operation of contacts IR-6 and the paper stop magnets SSM, Fig. 34e, are again energized through the relay contacts SB-5.

If the sheet is more than 4" in length than interlock relay R44, Fig. 34d, will be picked up through a circuit including line 151, cam contacts CR57, plug connection, carriage relay contacts R378-4, relay contacts S1-4, relay contacts R375-3 and pickup coil of magnet R44 to line 150. The consequent action of relay R44 causes transference of contacts R44-7 and the impulse to the latching control magnet IR is then through cam contacts CR87 at 340° rather than through cam contacts CR86 which close at 180°.

If the information to be printed on line 1 of a sheet is contained on a multiple line tabulating card and is to be printed by the "B" printing element then the transcriber circuits are established to pick up a relay R377, Fig. 34c; relay contacts R377-3, Fig. 34d, are then transferred and the circuit to the latch tripping coil IR of the interlock relay is then as follows: from the line 151, cam contacts CR87, transferred relay contacts R377-3, relay contacts SB-3, relay contacts R382-3, and then to the latch tripping coil IR and line 151. This circuit causes tripping of the latches at 340°.

It was noted hereinbefore in connection with the mechanical description that the stacker mechanism is power operated to maintain minimum spacing between the stacked sheets or envelopes and the downwardly moving chains. The stacker clutch is provided to call into operation the spacing mechanism for moving the stacker guides backward as the sheets accumulate. The circuit for the stacker clutch magnet SCM, Fig. 34e, includes line 151, wire 185, the stacker advance contact SAC, magnet SCM and line 150. The circuit is completed through the switch SAC whenever the stacker is filling the space between the last sheet and the chains and the clutch is called into operation to provide a greater amount of clearance.

While there have been shown and described and pointed

out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. In a machine for feeding sheets, a magazine for holding the sheets, means for adjusting the magazine to hold sheets of various widths and lengths, a picker mechanism for taking the sheets out of the magazine one by one, means for operating on the sheet, a plurality of endless feed chains for carrying the sheets past said sheet operating means, a series of sheet grasping clips on the chains, means for shifting the magazine and chains relative to each other to handle sheets of different lengths, a clip opening and closing means, means for adjustably locating the last-mentioned means to vary the head spacing position of the first operating line, means for moving the chains, said moving means including a line spacing device and a two speed clutch for spacing and long feeding the sheets with accelerated and decelerated movement to and from the means for operating on the sheet, a stacker, and clip operating means at the stacker for opening the clips to deposit successive sheets off the chains and into the stacker.

2. In combination, a portable sheet feeding machine mounted on castors, a printing machine, latching clamp devices on said machines for lifting the feeding machine and clamping it against the printing machine, a magazine for holding the sheets, a picker mechanism for taking the sheets out of the magazine, a plurality of endless feed chains for carrying an advanced sheet past said printing machine, said chains having a path a portion of which is parallel with the clamped side of the printing machine, a series of sheet grasping clips on the chains, and means for opening and closing said clips to assemble successive sheets on the chains.

3. In a machine for feeding sheets, a magazine for holding the sheets, said magazine being open at the top and one side, a series of hollow vacuum arms pivotally mounted near the open side of the magazine, means for rocking said arms toward and away from the leading sheet to bend out the leading edge, means for exhausting the air in said arms, a series of sets of feed rollers, an oscillating holder for said rollers, a fixed set of feed rollers with which the first mentioned rollers cooperate, means for rocking said holder in timed relation with the rocking of said arms to place the bent leading sheet edge in the bight of the rocked feed rollers, means for rotating the rollers, a plurality of feed chains, sheet engaging clips thereon, and guide means cooperating with the rollers for transferring an advanced sheet from the rollers to the clips on the chains.

4. A machine of the kind set forth in claim 3 and wherein one set of said series of feed rollers is flexibly mounted on said oscillating holder, a lever for moving said flexibly mounted rollers away from the fixed rollers, means for making minute adjustments of said lever to provide for roller settings for various thicknesses of sheets, and other means for making a wide adjustment of said lever to open the flexibly mounted rollers to relieve sheet jams.

5. In a machine for operating on a series of sheets, a magazine for holding said sheets, means for picking said sheets out of said magazine one by one, a pair of endless feed chains, sheet holding clips on said chains, means for operating said clips to hold successive sheets on said chains, means for advancing said chains to feed said sheets, a feed control tape with a plurality of sets of feed control indicia for controlling the positioning of said sheets, each of said sets of indicia including a plurality of related indicia corresponding to one position of the sheet, means for advancing said tape in synchronism with

the advance of the chains, means for operating said advancing means at different speeds, means for sensing said feed control indicia and means under control of said sensing means for operating said advancing means at graduated speeds for bringing said sheets to predetermined positions with accelerated and decelerated motion.

6. In a machine for operating on a series of documents a magazine for holding said documents, a plurality of endless chains upon which said documents are assembled successively, a feed control tape with indicia for controlling the feeding of the chains, means for advancing said chains and said tape in synchronism, a driving means for said advancing means, a series of three clutches between said driving means and said advancing means one of the said clutches being of the positive type and the other two being of the frictional type with different gear ratios for different speeds, means for sensing said tape indicia, means under control of said sensing means for controlling said friction clutches to control the speed of operation of said chains, and means for operating said positive clutch to engage and disengage with the driving means to control the exact stopping position of said chains and sheets.

7. In a machine for printing on sheets, a magazine for holding said sheets, means for picking said sheets out of said magazine one by one, a platen, a plurality of endless feed chains upon which said sheets are assembled successively and brought thereby to and away from said platen, an endless feed control tape of a length corresponding to the length of one of said sheets plus space between sheets, said tape having feed control perforations and tape advancing perforations, a sprocket wheel engaging said tape advancing perforations to move the tape connections between said chains and said tape sprocket wheel to move them in synchronism, a driving means, a series of clutches between said driving means and said connections, a plurality of said clutches being of variable speed variety and one being of a positive drive type, and means under control of said tape feed control perforations for operating said clutches to start and stop the advance of said chains and bring said sheets to predetermined print receiving positions at graduated speeds.

8. In a sheet feeding device, a driving means, a two speed clutch comprising two sets of clutch plates and separate face cams for wedging either of said set of plates together, separate arms on said face cams for operating them, a link connecting said arms, said link being held normally with the cam of the slow speed clutch effective a shifting cam for operating said link, a clutch therefore a magnet for releasing said clutch to operate the shift cam to shift the link to release the slow speed plates and engage the high speed plates, a latch for holding the shifted high speed operating arm in the shifted position, a magnet for controlling said latch, connections between said clutches and a means for advancing said sheets, and means for controlling the energization of said magnets to shift, hold and release the connections for changing from slow speed to high speed.

9. The combination set forth in claim 8 with record cards bearing feed control indicia, means for sensing said indicia, and means under control of said sensing means for controlling the energization of said magnets and said arm shifting means to operate short sheet advances at slow speed and long sheet advances at combined slow and fast speed with a slow start and slow finish of the long sheet feed.

10. The combination set forth in claim 8 with a feed control tape bearing related early and late speed control indicia, means for sensing said indicia and means under control of said sensing means for operating said magnets to control the speed shifting means.

11. In a record controlled machine for operating on a series of successive sheets, said records bearing indicia to control the advance of said sheets, means for analyzing said records, a magazine for holding said sheets, means

for picking said sheets out of said magazine one by one, a plurality of endless feed conveyors upon which said sheets are assembled successively, a feed control tape with pairs of indicia to control the advance of feed conveyors to various stopping positions, means for sensing the early and late indicium on said tape, means for advancing said conveyors and said tape in synchronism, means under control of said record analyzing means for selecting a pair of related tape sensing means one of which detects an early indicium on said tape, a multiple speed feeding means, means under control of the selected tape sensing means for varying the speed of said advancing means according to the length of the selected advance of the sheet, and means under control of the related selected tape sensing means in cooperation with said late indicium for controlling said advancing means to stop each sheet in predetermined positions related to the data on the controlled records.

12. In a sheet feeding device, fixed feed rollers, other feed rollers shiftably mounted to cooperate or open with respect to the first mentioned feed rollers, a movable mounting for the shiftable rollers, a sheet path defining means including guide tapes certain of which are held at one end, a shiftable bail carrying said tape ends, a lever for operating said roller mounting, means for simultaneously operating said bail and said lever to lift the guide tapes and open the shiftable rollers to relieve sheet jams.

13. The device set forth in claim 12 with an additional means for operating said lever to shift the shiftable rollers and adjust for a predetermined thickness of sheet.

14. In a sheet feeding machine, a pair of fixed frames, sheet conveyors within said frames, a pair of movable frames slidably mounted on said fixed frames, a sheet magazine on said movable frames to receive sheets of different lengths, a sheet picker mechanism on said movable frames, a driving means for the conveyors and picker including belting and two pulleys on the movable frames arranged to guide the belting in a shiftable S-shaped path, a platen past which said conveyors carry a sheet, sheet grasping means on said conveyors, a shiftable frame with operating means for said grasping means, said shiftable frame carrying conveyor guides around which the conveyors described a shiftable S-shaped path, whereby sheets of different lengths are grasped at different points relative to the platen to have different head spacings.

15. In a sheet feeding machine, main frames, endless

feed chains with sheet grasping means thereon, a platen past which the chains carry the sheets, shiftable frames for the chains adjustable relative the main frames to receive sheets of different widths, means for bringing the sheets successively to the grasping means, means for operating the sheet grasping means, a pair of carriers therefor, means for shifting said carriers along the chains relative to the sheet bringing means, and other means for shifting said carriers with the shiftable frames, whereby sheets of different widths and different heading spaces relative to the platen may be grasped by common grasping means.

16. A machine of the kind set forth in claim 15 and in which said operating means for the grasping means includes a pair of sheet stops, electrical control means for lowering and raising said stops, said sheet grasping means includes normally closed rockable clips on the chains, a pair of rollers for rocking open clips on opposite chains, electrical control means for putting said rollers in and out of the paths of the clips, and electrical coordinating means for timing both control means to operate the clips and stops in proper sequence.
